UNITED STATES PATENT OFFICE.

TALBOT G. MARTIN, OF CHICAGO, ILLINOIS, ASSIGNOR, BY MESNE ASSIGNMENTS, TO AUTOMATIC ELECTRIC COMPANY, A CORPORATION OF ILLINOIS.

PARTY-LINE TELEPHONE SYSTEM.

Application filed July 20, 1905. Serial No. 270,591.

To all whom it may concern:

Be it known that I, TALBOT G. MARTIN, a citizen of the United States of America, and resident of Chicago, Cook County, 5 Illinois, have invented a certain new and useful Improvement in Party-Line Telephone Systems, of which the following is a specification.

My invention relates to automatic telephone exchange systems in general, but more particularly to those systems in which the central station or exchange apparatus comprises a suitable number of electrically-propelled and step-by-step-actuated switch-10 ing machines, and especially to automatic telephone systems of this type in which the current employed by the subscribers for operating the switching apparatus at the central station or exchange is supplied from 15 a battery or other source which is common to all of the different subscribers' lines in the system, or at least to a certain number of such lines, according to the conditions and requirements of different cases. In the 20 type of automatic telephone exchange system to which my invention more particularly relates, each subscriber is provided with switching means termed a calling device—that is, a device by which he calls 25 the number of any other subscriber; and it will be understood, of course, that each subscriber's equipment comprises also a transmitter, a receiver and hook-switch, together with a bell or other suitable call-signal. In 30 systems of this character, each subscriber's line terminates in more or less apparatus which is individual to the line—that is to say, each subscriber's line runs from a subscriber's station to some point at or near 35 the central station or exchange, or to some other outlying point, and there terminates in apparatus having certain parts or devices which are individual to that line, and which are used by the subscriber of that 40 line and no other. For example, each subscriber's line may terminate in an electrically-propelled and step-by-step-actuated switching machine of the type known as a "first-selector", each "first-selector" being 45 individual to its allotted subscriber's line, and constituting a piece of switching apparatus which is used by that subscriber and no other. In addition, in a system of this 50 character, there may be other similar switching machines known as second or third or 55

even fourth "selectors", each of which is more or less common to the different subscribers, or to a certain proportion of the entire number of subscribers. Also, in an exchange comprising switching apparatus 60 whereby one subscriber may connect his line with the line of another subscriber, without the assistance of an operator at the central station, there is preferably another class of electrically-propelled and step-by- 65 step-actuated switching machines of that type known as "connectors".

The "selectors" are each employed for automatically selecting an idle trunk-line leading to the desired group of switching machines, either "selectors" or "connectors," according to the size and capacity of the exchange; but a "connector" is adapted and employed for making the final connection directly with the line of the called subscriber. Consequently, any calling subscriber may operate his calling device, so as to call the number of the called subscriber, and thereby produce such operations on the 70 part of certain of the switching machines in the exchange as will connect his line with the called subscriber's line, providing, of course, that the called subscriber is not already using his line, or that some other subscriber has not already connected his line 75 with that of the called subscriber. The calling of any desired number consists, it will be understood, in simply producing a make-and-break action in a grounded "line-circuit" including one side of the calling sub- 80 scriber's line, and in another grounded circuit including the other side of the calling subscriber's line. For example, if the calling subscriber desires to connect his line with that of another subscriber whose number is 85 410, the operation of calling the desired number is as follows: The calling subscriber momentarily closes one of the ground-circuits four times in succession, so as to produce four distinct and successive electrical 90 impulses in the said circuit; and preferably, and in a system of the character to which my invention more particularly relates, he then follows these four electrical impulses with a single impulse in a ground-circuit including 95 the other side of his line, so as to not only cause his "first-selector" to pick out the desired group of trunk-lines, but also to then pick out and connect his line with the first 100 trunk-line of this group which is found to 105 110.

be in an idle or non-busy condition. In other words, the calling subscriber's "first-selector" responds to the four impulses and proceeds, under the direct control of the 5 calling subscriber, to pick out the desired group of trunk-lines; but at this point in its operation, the said "first-selector" escapes, so to speak, from the control of the calling subscriber and proceeds automatically and by 10 itself to pick out and establish connection with the first trunk-line in the group which is found to be idle and in condition to be appropriated by the calling subscriber as a means of establishing connection between his 15 line and that of the called subscriber. This means accomplished in the switching operation by which the calling subscriber, by his own acts and without the assistance of an operator, connects his line with the line of 20 the called subscriber, the said calling subscriber then operates his calling device in such manner as to first transmit a single impulse over one side of the line, this operation corresponding, it will be observed, to 25 the second digit of the called subscriber's number; and this is followed, of course, by the single impulse over the other side of the line. This single impulse transmitted over the so-called "vertical" side of the "line-circuit" is received by or transmitted through 30 the apparatus of a "connector" situated at the end of the trunk-line which was automatically selected by the "first-selector." Accordingly, the said "connector" responds by 35 picking out the group of subscribers' lines in which the called subscriber's line is included; but it will be seen that the "connector" must now complete the work for which it has been appropriated by the calling subscriber—that 40 is, must find the exact subscriber's line with which the calling subscriber desires connection. Now it will be seen that in the case of a "selector," the first part of the operation thereof was under the direct control of the 45 calling subscriber, while the remainder of the operation, which consisted in making connection with the trunk-line, was accomplished automatically by the "selector" and without the aid of the calling subscriber. 50 With the "connector," however, the situation is quite different; for the establishment of connection between the two subscribers' lines has now arrived at a point where it is simply a matter of making connection with a 55 certain subscriber's line and no other, as the calling subscriber, of course, desires to establish connection with this particular subscriber's line. While the calling subscriber was extending the connection from his line 60 to a "connector," it mattered little to him how that connection was made, or over which of the many trunk-lines that connection was accomplished; for with quite a number of trunk-lines extending between the different 65 groups of switches, the calling subscriber is not concerned with the manner in which his line is finally connected with a "connector"—that is to say, any one of a certain number of trunk-lines may be used, and any arrangement will serve his purposes so long as a 70 connection is finally established with one of a certain number of "connectors" each of which is capable of establishing connection directly with the line of the called subscriber. It is for this reason, therefore, that 75 the entire operation of a "connector," in establishing the desired connection, is under the direct control of the calling subscriber, so that he may not only cause the "connector" to pick out the particular group in 80 which the called subscriber's line is included, but may also then cause the "connector" to pick out and establish connection with the particular or desired line in such group. Consequently, the calling subscriber now 85 completes the operation of the "connector" by so operating his calling device as to transmit ten successive electrical impulses over one side of the "line-circuit," this operation corresponding to the cipher or last digit of 90 the called number; and these ten electrical impulses transmitted over a grounded "line-circuit" including one side of the line are then followed immediately by the single impulse transmitted over the other side of the 95 line, as will hereinafter more fully appear. This final operation completes the connection between the calling and the called subscribers' lines, and the calling subscriber may then press his so-called ringing-button and 100 thereby cause a relay in the "connector" to temporarily connect the so-called ringing-generator with the line of the called subscriber, thus ringing the bell at the called subscriber's station. In this example of the use of a 105 subscriber-operated exchange apparatus for automatically establishing connection between subscribers' lines, it will be observed that the system involves only a comparatively small number of subscribers, thereby 110 rendering the employment of intermediate "selectors" unnecessary; for unless the calling subscriber desires to call a subscriber whose number contains four or more digits, no second or third or fourth "selectors" are 115 necessary in completing the connection between the "first-selector" and the "connector." Furthermore, in an automatic telephone system of the character to which my invention relates, it is the practice to so construct and organize the switching machinery and circuits that any trunk-line, after once being appropriated for use by a calling subscriber, will be fully protected against seizure by some other subscriber; and this is also 120 true of any subscriber's line which is in use, as it is obviously desirable that a calling subscriber's line be protected against seizure during the time he is endeavoring to communicate with the called subscriber, and 125 130

that a calling subscriber's line be protected against seizure by a third subscriber before the called subscriber answers; and while the two subscribers are conversing, the two lines and the trunk-line connection by which they are connected, and in fact the entire talking-circuit thus temporarily established between the two subscribers, must be made immune against seizure by other subscribers 5 as well as against listening-in on the part of other subscribers. Again, the construction and arrangement is preferably such that a calling subscriber can release any and all of the switches which he may 10 have put in operation, either before or after the calling subscriber answers, and it is also desirable that the called subscriber be able to at least restore the "connector" and thereby disconnect his line from that of the 15 calling subscriber; and it is even the practice generally to so construct the apparatus that either the calling or the called subscriber may effect a complete and total release and restoration of all switching machines which 20 may have been employed in establishing connection between their two lines. The current for talking purposes may be furnished either by local batteries at the subscribers' stations, or by a centralized source 25 of supply; but the current for operating the switching machines is preferably furnished from the battery or other centralized source of supply, and the current for ringing the bells at the subscribers' stations is also preferably derived from suitable generating 30 means at the exchange or central station.

Generally stated, the object of my invention is the provision of an improved construction and arrangement whereby an automatic telephone system of the foregoing 35 character, or of substantially the foregoing character, may be operated on the party-line basis, so that one or more of the subscribers' lines therein may be provided with a plurality of subscribers' stations, and whereby any subscriber may establish connection with any such party-line and signal the desired subscriber on that line, or whereby any subscriber on a party-line may 40 signal and communicate with another subscriber on the same line. Special objects of my invention are to provide an improved construction and arrangement for selectively signaling the different subscribers on a party-line in an automatic telephone 45 exchange system of the foregoing character; to provide an improved construction and arrangement whereby, in an automatic telephone exchange system, the different subscribers on a party-line may each have a different number, and whereby any calling subscriber may call any one of these numbers and obtain connection with such party-line, but whereby the bell at the called subscriber's station will always ring to the 50 exclusion of all other bells on the same line; to provide an improved construction and arrangement whereby several subscribers on the same line may be selectively called or signaled through the medium of a plurality of groups of "connectors," said groups corresponding in number to the number of subscribers on the line, and whereby the employment of any "connector" in any group by a calling subscriber will accomplish the 55 same result, as far as connective purposes are concerned—that is, will establish connection with the party-line—but whereby the use of any "connector" will inevitably result in the transmission onto the party-line of a ringing current of such character that only one bell will ring, namely the one at the sub-station which corresponds to the "connector" in use, or which corresponds, more properly speaking, to the group of 60 "connectors" in which is included the particular "connector" by which the calling subscriber establishes connection with the party-line; to provide an improved construction and arrangement by which connection may be established with a party-line through the medium of a plurality of groups of "connectors," there being as many groups as there are subscribers' stations on the party-line, and the contacts or line-terminals which are allotted to one subscriber's station, and which are multiplied together horizontally in a certain level of a certain group of "connectors," being cross-multiplied 65 vertically with the groups of contacts or line-terminals which are allotted to the other stations on the same line, and which are located in corresponding levels in the other groups of "connectors," the contacts or line-terminals representing one subscriber's station being located, for example, in the first level of the banks of a certain group of "connectors," those belonging to another subscriber being located in the same level of the banks of another group of "connectors," and so on, each subscriber's station 70 being given a set of multiple-contacts or line-terminals which are located in the first level of the particular hundred-group of "connectors" to which the subscriber belongs, and each of the different groups of "connectors" which are allotted to the different hundred-groups to which the different subscribers of the party-line belong being equipped for transmitting a different kind of 75 ringing current, whereby any "connector" in any of the said groups is operative to establish connection with the said party-line, but whereby whenever a connection is thus established only that bell will ring which 80 belongs to the called subscriber—that is, the subscriber whose station corresponds to the particular group of "connectors" in which is included the "connector" which was automatically connected with the calling sub- 85 90 95 100 105 110 115 120 125 130

scriber's line, in accordance with the character of the called subscriber's number, and by which the final connection is established directly with the party-line on which the 5 called subscriber's station is located; to provide an improved construction and arrangement whereby any subscriber, particularly a party-line subscriber, may temporarily or momentarily remove the guarding potential 10 established through the "private-bank-contacts" of his "first-selector" when he momentarily grounds the so-called "rotary" side of his line—as, for example, in completing the operation of a "connector" for 15 the purpose of closing connection with the line selected by the "connector"—whereby a party-line subscriber may employ the proper "connector" for calling and signaling another subscriber on the same line, it being 20 observed that in such case the calling subscriber must, so to speak, call his own line and thereby compel the "connector" to make connection with a line which is busy, and which is in condition to ordinarily defeat 25 any attempt on the part of a "connector" to establish a connection therewith; and to provide certain details of construction and features of improvement and combinations tending to increase the general 30 efficiency and serviceability of an automatic party-line telephone exchange system of this particular character, and to advance the art of telephony generally.

To the foregoing and other useful ends, 35 my invention consists in matters hereinafter set forth and claimed.

A brief description of the accompanying drawings is as follows:

Figures 1, 2 and 3, taken together, 40 represent in diagram the circuits and mechanical details involved when one subscriber has called another. The sub-station A in Fig. 1 (No. 500) is shown as having called sub-station No. 410 in Fig. 3. At B (Fig. 1) 45 there is represented the "first-selector" of the calling subscriber in its connective position in the circuit. In Fig. 2, C¹⁰ indicates the position of the "connector" which has completed the circuit, and which is a member 50 of a group of "connectors" that use current for ringing purposes from a suitable generator D. Another "connector" of another group is indicated at E¹⁰, and this latter "connector" uses current from another 55 generator F. The "connector" of another group is shown at G¹⁰, which uses current for ringing purposes from the group generator H. And still another "connector" is shown at I¹⁰ with its particular group ringing generator J.

Fig. 3 is a diagrammatic drawing of a party telephone line to which there are connected four sub-stations, their numbers being 60 110, 210, 310 and 410, as designated. 65 These stations have a "first-selector" K in

common, and may call each other selectively. Also a party of another line may be called by them individually, or he may call any of them selectively. These operations will be fully described hereinafter.

Fig. 4 is a diagrammatic perspective view of the "first-selector" B, showing the circuits and operative parts of the mechanism, omitting the switch-frame. Underneath the switch the "private" and the "line" banks 75 are shown, the former above the latter.

Fig. 5 is a diagrammatic perspective drawing of the "connector" C¹⁰.

Fig. 6 represents the sub-stations 110, 210, 310 and 410 of Fig. 3, where one of said sub-stations (No. 110) has called another subscriber (No. 410) on his own line.

The construction and general operation of the different devices and switching machines are as follows:

The "first-selector" K, which is the same as "first-selector" K of Fig. 3, is shown operated and connected with the connector C¹⁰, which latter is the same as "connector" C¹⁰ of Figs. 2 and 5. "Connector-groups," 90 such as the ones represented in Fig. 2, may correspond in number to the maximum number of subscribers which the exchange can maintain on a single line. This arrangement is necessary in order that access may 95 be had to a different ringing generator for signaling a different subscriber on each party line. The bell or ringing apparatus at each telephone is so adjusted that only alternating current of a particular frequency will affect each one of them; and the frequency that will affect one of the sub-stations on the line will not affect any of the others on the same line. Therefore, if there 100

are four parties on one line, to signal each one there is required current of four different frequencies; and there are required, therefore, the services of four different generators, and consequently four different "connector-groups" must have access to the 105 line to which the four parties are connected. This arrangement is clearly indicated in Figs. 2 and 3. The "connectors" C¹⁰, E¹⁰, G¹⁰ and I¹⁰ belong respectively to the so-called 400, 300, 200 and 100 groups. 110 It will be seen that the "connector" C¹⁰ is connected to the tenth terminal of the fourth level of the "line-bank" of the "first-selector" B (Fig. 4), and that "connectors" E¹⁰, C¹⁰ and I¹⁰ are connected, respectively, to the 115 tenth contact of the third, second and first levels. In Fig. 2 the conductors 2, 3 and 4 connect in multiple all corresponding tenth "bank-contact-points" of the "400-connector-banks," similar to the banks shown in Fig. 120 4. Opposite each set of these banks there is a "connector" parallel with "connector" C¹⁰. These latter, in regular order, are connected by trunk-lines to corresponding contacts of the fourth level of the "first-selector" 125

130

banks" parallel with the trunk-lines of "connector" C^{10} . The trunk-line leading from the first contacts of the fourth row or level of the "first-selector" B, for instance, would 5 terminate in "connector" C^1 , the position of which "connector" is opposite the bank-contacts c^1 ; and the trunk-lines from the second, third, etc. in the "connectors" C^2 , C^3 , etc. positioned between "connectors" C^1 and C^{10} . The same arrangement applies with respect to the E or 300-group, as well as to the other two succeeding groups. Not only are all the corresponding tenth contact-points of the fourth level of each group in 10 each hundred connected in multiple, but they are also connected in multiple between hundreds by conductors, as is indicated by the lines 5, 6 and 7. A similar construction is true of all other corresponding contact-points. If there should be only three parties on a line, it is evident that it would be necessary to cross-multiple only three of the hundreds, such, for instance, as the four-hundred group, the three-hundred group 15 and the two-hundred group.

Any subscriber desiring connection with the "party-line" subscriber No. 410 must use the ringing current generator of the four-hundred group. The calling "first-selector", therefore, is raised to the fourth level, and an idle "connector" of that group is selected. It has been explained that all the "connectors" of the four-hundred group terminate in the fourth level of the "first-selector-banks", and that they draw their ringing current from ringing generator D. Then if the "connector" C^{10} is selected, it is raised to the first level and rotated ten steps, placing the calling line in connection 20 with the trunk-conductors 6 and 7 and, therefore, with sub-station No. 410 (Fig. 3). As the bell of only this sub-station is adjusted to respond to the current of ringing generator D, only said bell will respond to 25 the ringing current therefrom. If party No. 310 is desired instead, the "first-selector-wipers" are then raised to the third level of the bank-contacts and "cut-in" onto some "connector" of the three-hundred of E- 30 group—that is, these "selector-wipers" are caused to stop on contacts connected with a "connector" of said particular group. After the circuit is completed, the current from the ringing generator F is projected 35 onto the same line, but only the bell or ringing apparatus of sub-station No. 310 will respond to that current, as the other bells or ringing devices are not adjusted to respond to the ringing current from this group. 40 Similar arrangement applies to the calling of subscribers No. 210 and No. 110, which would require, respectively, ringing current from generators H and J. The various battery representations refer to only one battery, the positive terminal of which prefer-

ably is grounded. All of the sub-stations are constructed the same, with the exception of the ringers or bells, and in Figs. 1, 3 and 6 like parts are represented similarly. Each sub-station, Fig. 1, for instance, is provided with the usual receiver 8, switch-hook 9, ringer 10, transmitter 11, induction-coil 12, local battery 13, and a condenser 14. The induction-coil, of course, is made up of a primary and a secondary winding 15 and 16, respectively. The switch-hook is designed to control the local-circuit-springs 17 and 18, the secondary-circuit-springs 19 and 20, and the ground-circuit-springs 21 and 22. In addition, the subscriber's telephone 25 apparatus is furnished with a signaling-button 23 which may be pressed against the spring 24 that is normally closed with contact-point 25. When said button is pressed, the spring 24 breaks with contact-point 25 and closes with contact-point 26. The calling device at each telephone may be of any well-known or suitable type, and is simply represented in Fig. 1 by two push-buttons 27 and 28, two springs 29 and 30 and three 30 contact-points 31, 32 and 33. The "first-selector" of my invention may be of any well-known or suitable type, such, for instance, as the "first-selector" B represented in connection with sub-station A, Fig. 1. The 35 mechanism and circuits of this "selector" are clearly shown in Fig. 4. The line-conductors 34 and 35 of sub-station A terminate at this switch in certain relays. The "vertical-line-conductor" 34 is connected with the relay 40, which is known as the "vertical-line-relay", and the "rotary-line-conductor" 35 terminates in the second relay 41, known as the "rotary-line-relay". Through their armatures—the "vertical-relay-armature" 42 and the "rotary-relay-armature" 43—these relays have supervision over the so-called "line-relay-springs" 44, 45 and 46, and over certain internal circuits which are hereinafter described. For 40 example, one of these circuits includes an electro-magnet known as the "vertical-magnet" 47, which consists of two coils 48 and 49. These coils and their cores, when energized, operate an armature 50 which is supported from the switch-frame by two pivots 51 and 52. Said armature is normally held away from the "vertical-magnet-pole-pieces" by a retracting-spring 53. When 45 this armature is actuated, it operates certain devices through the medium of an arm 54, which latter constitutes part of said armature and is known as the "vertical-arm". This arm has on its lower side an L-shaped piece 55, and on its forward end a pawl 56 known as a "vertical-pawl" 56, which latter is pivotally secured to said end. This pawl is held in position by a small retracting-spring 57, one end of which spring is attached to the rear end of the "vertical- 50

pawl", and the other to the body of the "vertical-arm" 54. A second electro-magnet, indirectly controlled through the "line-relay-springs" is the "rotary-magnet" 60. 5 This "rotary-magnet" is provided with two coils or windings 61 and 62, and operates certain mechanism through an armature known as the "rotary-armature" 63, said armature being supported from the 10 switch-frame, in a vertical plane, by two pivots 64 and 65. This armature performs its work while moving in an oscillatory manner under the influence of the magnetic force developed intermittently in the 15 "rotary-magnet", and of a retracting-spring 66, which latter returns said armature to its normal position after the magnetic force disappears. This armature is provided with three arms, as follows: 20 A so-called "interrupter-arm" 67 which works in conjunction with two springs 68 and 69 known as the "interrupter-springs"; the so-called "rotary-armature-finger" 70 which works in conjunction with the armature of another electro-magnet known as the "private-magnet"; and a so-called "rotary-arm" 71. This last arm has pivotally attached to its forward end a so-called "rotary-pawl" 72 which is subject to the 30 tension of a small coiled spring 73. One end of this spring is attached to the rearward end of the pawl, and the other to the "rotary-arm" 71. For the restoration of the switching machine, a so-called "release-magnet" is employed, which is usually composed of two coils; but for the sake of simplicity and clearness only one coil 74 is shown. This "release-magnet", like the "rotary" and "vertical" magnets, has placed 40 before its pole-piece an armature 75 which is pivotally supported from the switch-frame by two pivot projections 76 and 77. This armature is normally held away from its pole-piece by a coiled spring 78, and has attached to it a flexible blade-spring 79 known as the "release-link". This link lies horizontally under the "release-magnet", and passes between the "vertical-arm" 54 and the L-shaped piece 55, already 45 described. The forward end of this link is provided with an aperture 80 for normally holding the so-called "double-dog" 81, by its lug 82, against the pull of the "double-dog-retracting-spring" 83, when the switch 50 is released. This "double-dog" is supported from the "switch-frame" by pivots 84 and 85, and is provided with two locking-arms 86 and 87, and with a third and downwardly-projecting arm 88, the office of 60 which latter will be disclosed later on. The "private-magnet", to which reference has already been made, is composed of only one coil 90. Its armature 91 is supported from the "private-magnet-frame" (not shown), 65 and works in a vibratory manner about a

horizontal axis that passes through the supporting-pivots 92 and 93. The "private-magnet-armature" 91 is formed with a forwardly-projecting arm 94 having two flat surfaces disposed in a horizontal plane. 70 Said arm has a short length 95 at its forward extremity bent downwardly at right angles thereto. This arm 94 carries certain mechanical details, as follows: A lateral arm 96, designed to control the relation of 75 three springs 97, 98 and 99, known as the "private-springs"; a tooth escapement which includes two flexible springs 100 and 101, each of which springs is riveted by one end to the "private-armature-arm", one on 80 the upper side and the other on the lower. The upper spring is straight and has formed near its forward end two downwardly-extending tooth-like projections 102 and 103; but the under spring is bent at 85 right angles, first downwardly and then at right angles again to the front. This double angle in this lower escapement-spring is so formed that said lower spring may clear the bent portion 95 of the 90 "private-armature-arm" 94, against which portion it rests with a certain amount of tension, and so that there may be space to receive two other tooth-shaped upwardly-projecting pieces 104 and 105, which are 95 formed on the forward end of this escapement-spring, and which are situated in juxtaposition to and slightly to the rear of the upper teeth. A retracting-spring 106, which has one end attached to the "private-armature" normally holds said armature away from the "private-magnet-pole-piece". In conjunction with this escapement just described, there is a finger 108 at the right end extremity of a so-called "side-switch-arm" 109 normally retained behind the rearmost tooth of the lower escapement-spring. This "side-switch-arm" has, near the base of the "side-switch-finger" 108, a small forwardly-bent lug 110. The arm 109 105 may be made to oscillate about the pivotal points 111 and 112, provided near its middle, and which have a common vertical axis. This "side-switch-arm", to the left of its center, carries a rearwardly-projecting member 113 to the extremity of which is pivotally secured a link 114. The other end of said link is bifurcated and engages the lower T-shaped extremity of the straight arm 88 on the "double-dog" 81. Very near 110 the left extremity of the "side-switch-arm" there rises a shaft 115 which supports a number of wipers 116, 117, 118, 119 and 120, known as the "side-switch-wipers". These wipers, which are secured rigidly to the 115 "side-switch-arm", may be made to assume any one of three positions, and each is normally in position to engage one of a series of contact-points, as follows: 121, 122 and 123; 124, 125 and 126; 127, 128 and 129; 130, 120 125 130

131 and 132; 133, 134 and 135. The "side-switch-arm" 109, with all its associated parts, is known as the "side-switch"; and when the finger 108 that works in conjunction with the tooth escapement is in its rearmost position, the "side-switch" is said to be in the first or normal position; when between the front and rear teeth, the "side-switch" is then said to be in the second position; and when said "side-switch" is in the third position the finger 108 is in front of or outside of all of these teeth and rests against the so-called "side-switch-stop" 136. When in the first position, the wipers 116, 117, 118, 119 and 120 are respectively in contact with the contact-points 121, 124, 127, 130 and 133 in their order; but when in the second position, these wipers engage with contact-points 122, 125, 128, 131 and 134, 20 and in the third position with contact-points 123, 126, 129, 132 and 135. The force that operates the "side-switch" in a forward direction resides in a retracting-spring 137 fastened at one end to the switch-frame, and at the other end to the "side-switch-arm".

One of the characteristic parts of the switch is a shaft 140 that has provided near its middle a set of circular or so-called "vertical-ratchet-teeth" 141 traversed by a vertical or longitudinal channel 142, into which there projects the extremity of a so-called shaft-rest 143. Below the said circular or "vertical-ratchet-teeth" is located a set of longitudinal or so-called "rotary-ratchet-teeth" 144 through the medium of which the shaft is given a step-by-step rotary motion. Just below these teeth there is a cam-piece 145 which prevents the "side-switch-arm" 40 from escaping too far when it is shifted from the first to the second position, as will be more fully explained. Near the lower end of the shaft are supported the "rotary" and "vertical" "line-wipers" 146 and 147, 45 which are insulated from each other and from the shaft. Just in front of these wipers is the "line-bank" 148, and just above them the "private-wiper" 149, in front of which latter is located the "private-bank" 150. There is a coil-spring 151 fastened near the upper end of the shaft with its outer extremity secured to a so-called guide or stop-pin 152. This spring retains said shaft in its normal position. Just below 50 this spring there is an arm 153 known as the "normal" or stop-arm, which prevents the shaft from being rotated by said coiled spring beyond a certain point. Said stop-arm retains the channel along the circular teeth, when the wipers are disengaged from the bank-contacts, in such a position that the shaft may be raised or lowered without any interference on the part of the shaft-rest. Said "normal-arm" 153 also controls 55 the position of a so-called "normal-spring" 154 with respect to two contact-points 155 and 156 between which said "normal-spring" is situated. If electric pulsations are sent through the "vertical-magnet" 47, the "vertical-armature" 50 is attracted—that is, once 70 each time the magnet is energized by a pulsation or momentary closing of the circuit. At the first impulse or momentary closure of the circuit, and the consequent attraction of the "vertical-armature," the "vertical-pawl" 75 56 engages with one of the circular or so-called "vertical-ratchet-teeth," thus raising the shaft one step. At the same time the "vertical-arm" 54 disengages the release-link 79 from the "double-dog" 81 by means of 80 the L-shaped piece on said "vertical-arm." As soon as the "double-dog" 81 is released, the upper and lower locking-arms 86 and 87 fall against the circular and the "longitudinal-ratchet-teeth," respectively. The 85 upper locking-arm catches the shaft in its raised position and retains it there when the "vertical-armature" returns to its normal position after the "vertical-magnet" is de-energized. On the second impulse the 90 shaft is raised another step and again caught by the upper locking-arm, and is so actuated each time the "vertical-magnet" is energized. If, immediately after the shaft is raised, the "private-magnet" 90 should be 95 energized once, the finger 108 on the "side-switch-arm" will then disengage from the rearmost tooth of the lower escapement-spring 101 upon the downward stroke of the armature 91, and engage with the rearmost 100 tooth of the upper escapement-spring. Upon the return of said armature to its normal position, the finger 108 will disengage in turn from the upper rearmost tooth, permitting the "side-switch" to be drawn to 105 the second position by the "side-switch-retracting-spring" 137. The lug 110 on the "side-switch-arm" then strikes the cam-piece 145 on the shaft and prevents a further advance of said "side-switch," for the time being. After the "side-switch" is shifted to the second position, the step-by-step rotary motion of the shaft is then brought about in a slightly different manner from the vertical motion. For instance: When a circuit is 115 closed through the "rotary-magnet" 60, it includes the interrupter-springs 68 and 69. The "rotary-armature" 63, upon being attracted, causes the "rotary-pawl" to engage with one of the "longitudinal-ratchet-teeth," 120 and the shaft is thereby rotated one step. In this advanced position the shaft is retained by the lower locking-arm 87 of the "double-dog." Immediately after the shaft is locked, the interrupter-arm 67 separates 125 the interrupter-springs, and the energizing circuit of the "rotary-magnet" is thus broken. It is evident that the "rotary-armature" 63 will then return to its normal position under the tension of the "rotary-arma- 130

ture-retracting-spring" 66. If the circuit through the "rotary-magnet" has not been broken at any other point, as soon as the interrupter-springs re-engage after the interrupter-finger is withdrawn from between them, the "rotary-magnet" will be re-energized, and the shaft will be rotated one more step, and so on until the circuit through the "rotary-magnet" is broken permanently elsewhere.

When the shaft is rotated, the cam 145 is rotated with it out of the way of said lug 110, and the "side-switch-finger" 108 is then drawn against the front tooth 105 of the lower escapement-spring. If the "private-magnet" is energized once more, momentarily, the "side-switch-finger" 108 will disengage from the lower front tooth and fall against the upper front tooth 103 at the downward stroke of the armature, and from the upper front tooth at the return of the armature to normal position; and the "side-switch-arm" will be drawn to the third position against the "side-switch-stop" 136. There are two other relays associated with a "first-selector"; one is known as the "private-normal-relay" 160, which has control through its armature 161 of a number of circuits that are connected with the so-called "private-normal-relay-springs" 162, 163 and 164; and the other the so-called "bridge-cut-off-relay" 165. By means of the armature 166 of the latter relay, a number of circuits are opened, and other desired objects are attained in connection with circuits that include a number of springs 167, 168, 169, 170, 171, 172, 173 and 174. The release mechanism of the "first-selector" is controlled through the "release-magnet" 74. If the switch has been used, so that the shaft has been raised and rotated for instance, then when the "release-magnet" is energized the "release-armature" 75 is attracted, and as a result the release-link 79 is brought forward far enough to cause the lug 82 of the "double-dog" 81 to engage the aperture 80 in the forward end of said link. Then when the "release-magnet" is de-energized, the "release-armature" 75 is pulled back by the "release-armature-retracting-spring" 78. As a result, the "double-dog-locking-arms" 86 and 87 are drawn away from the circular and longitudinal ratchet-teeth on the shaft, and the "side-switch" is shifted to its first position by the "double-dog-arm" 88 and the intermediate link 114. The "side-switch-arm-finger" 108, when pushed back, separates the escapement-springs 101 and 100 sufficiently to open a path of movement for itself, and is finally caught behind the last lower tooth 104. When the "vertical-magnet" was energized for each step that the shaft was raised, the under surface of some circular ratchet-tooth was brought on a level with the upper surface of the shaft-rest 143,

and as soon as the shaft was rotated the circular tooth so raised rested and turned on the said shaft-rest. It is clear, then, that when the switch has been raised and rotated, and if the "double-dog" is drawn away from the ratchet-teeth in a manner described, the shaft will be left subject to the tension of the coil-spring 151. It will rotate then in a backward direction upon the shaft-rest 143, as before explained, until the stop-arm 153 strikes the guide-pin or normal-post 152. At this juncture, the shaft-rest again enters the channel 142, and the shaft by its own weight falls to its normal position. All "first-selectors" in the drawings are identical in structure, so that the "selector" shown at K, Figs. 3 and 6, has all its parts represented the same as the corresponding parts of the "first-selector" B, Fig. 1. Such parts are, for instance, the "vertical-line-relay" 59 and the "rotary-line-relay" 107, the "private-magnet" 138 and the "release-magnet" 139, the "private-normal-relay" 157 with its armature 158, the "vertical-magnet" 58, the "rotary-magnet" 39, the "private-normal-relay-springs" 159, 175 and 176, as well as the "line-switching-relay" 177 with its armature 178 and "line-switching-springs" 179, 180, 181, 182, 183, 184, 185 and 186. Between the "vertical" and "rotary" "line-relays" 59 and 107 are located the "line-relay-springs" 187, 188 and 189, and in addition the "normal-arm" 190 of the switch-shaft, together with the "normal-spring" 191 and the adjacent contacts 192 and 193 are clearly shown. The "side-switch-wipers", as they appear in Fig. 6, are represented at 194, 195, 196, 198 and 197. As will be observed, many of the mechanical details of the "connector" represented at C¹⁰, Figs. 2, 5 and 6, are the same as those of the "first-selector". For example, the "vertical-line-relay-magnet" 200 and armature 201, the "rotary-line-relay-magnet" 202 and armature 203, and the "line-relay-springs" 204, 205 and 206, the "vertical-magnet" 207, the "vertical-armature" 208, and the "vertical-arm" 209. Said "vertical-arm" is provided with the usual L-shaped piece 210 and the "vertical-pawl" 211. The armature 212 of the "rotary-magnet" 213 is, however, rendered conspicuous by the absence of the interrupter-finger and the "rotary-armature-finger" found in the "first-selector". The "rotary-armature" of the "connector" has only one arm, and that is the "rotary-arm" 214 that carries the well-known "rotary-ratchet-pawl" 215. The "private-magnet" 216, "private-springs" 217, 218, 219 and 220, and the controlling arm 221, may be clearly recognized. The escapement on the "private-armature" 222 differs slightly in that the upper escapement-spring 223 has only one tooth 224; the lower spring 225, however, has the usual two teeth 226 and 227. The "release-magnet" 228 and 130

the "release-link" 229 are clearly shown, but the release mechanism is arranged differently. The "release-armature" 230 is situated on the right-hand side of the "release-magnet", and is retained away from the "release-magnet-pole-piece", by a simple retracting-spring 231. The release-link, instead of being mounted on the "release-armature", is supported independently and permanently on some part of the switch structure. The "double-dog" performs the usual functions through its locking-arms 232 and 233 with regard to the shaft 234 and the circular and the longitudinal ratchet-teeth 235 and 236. The "side-switch" differs from the "first-selector-side-switch" only in the fact that there are four "side-switch-wipers" 237, 238, 239 and 240 instead of five. The restoration of these wipers, and of the "side-switch-arm" 241, is effected through the "side-switch-release-arm" 242 of the "double-dog", as in the "first-selector". The "side-switch-finger" 243 and the escapement of the "private-armature" work together in the manner described in connection with Fig. 4, except that the "side-switch" passes from the second to the third position against the "side-switch-stop" 244 at the downward instead of the return stroke of the "private-armature" 222. The switch-shaft "line-wipers" 246 and 247, the "line-bank" 248, the "private-wiper" 249 and the "private-bank" 250 are the same as in the "first-selector", as well as the cam 251 and the cam-stop 252 on the "side-switch-arm". When the shaft is rotated, it is supported on the shaft-rest 253 by the circular ratchet-teeth; and said rotation is accomplished against the tension of the coiled spring 254, which latter is fastened to the shaft by its inner end, and to the guide-pin 255 at its outer end. While the wipers are disengaged from the bank-contacts, the "normal-arm" 256 is held against the guide-pin or normal-post by the pull of the coiled spring, and in this way the shaft and all its parts are held in normal conditions. The release of the "connector" is brought about when the "release-magnet" 228 attracts the "release-armature" 230. Said armature, when attracted, thrusts the "double-dog" 257 into engagement with the release-link and away from the ratchet-teeth. The release-link falls over the lug 258 on the "double-dog", retaining the latter in its new position. The shaft, being left free, is rotated in a backward direction on the shaft-rest by the tension of the coiled spring. As soon as the "normal-arm" strikes the guide-pin or normal post, the arm-rest enters the channel 259 along the circular teeth and leaves the shaft free to fall by its own weight to its normal position. It will be noticed that the release of the "connector" is accomplished as soon as the "release-armature" is attracted; but this differs from the release

of the "first-selector", which latter, it will be remembered, releases only after the "release-magnet" is de-energized. The "normal-spring" 260 on the "connector" has only one contact-point 261 with which it engages whenever the shaft is raised from its lowest or normal position. In addition, the "connector" is provided with a so-called "back-release-relay" which is composed of two coils 262 and 263. Each of these coils has an armature indicated by the numbers 264 and 265, respectively. When these armatures are simultaneously attracted, the two springs 266 and 267 are closed, and thus employed to energize the "release-magnet" 268 of the "connector". Finally, there is a signaling or ringer-relay 268 which, after a connection is established, is energized when the calling subscriber presses the signaling or ringing button. The armature 269 of this ringer-relay, when attracted, separates the called subscriber's line from the calling subscriber's line and places the former across the terminals of a ringer-generator D. This is done through the medium of a number of springs 270, 271, 272, 273, 274 and 275, which the ringer-relay-armature has under its control. The four sub-stations in Fig. 3, designated as Nos. 110, 210, 310 and 410, are each the same in make-up as sub-station A, Fig. 1, with the exception of the ringers or bells; for preferably the ringers or bells at the different stations are of different construction, or are differently combined with other lines, so that each responds only to its allotted character of current, or to only ringing current intended for it. In Fig. 2, the "connectors" represented by the letters E¹⁰, G¹⁰ and I¹⁰ are the same as "connector" C¹⁰ and have similar parts similarly represented. These "connectors" use in common a busy signaling apparatus comprising a circuit-interrupter 276 and an induction-coil 277 with a primary winding 278 and a secondary winding 279; and having described the mechanical details and general operation of my system, the next step will be to describe its use in connection with the circuits. In actual use, the operations are as follows: Assuming that the subscriber at sub-station A (referring to Figs. 1, 2 and 3) wishes to establish connection with the subscriber at sub-station designated as No. 410, he (the calling subscriber) will first remove his receiver 8 from the switch-hook 9. As soon as the receiver is removed, the hook rises, owing to the tension of a spring which is not shown, breaking contact as it rises with the so-called ringer-spring 280, and closing the talking-circuit-springs 17 and 18, the secondary circuit-springs 19 and 20, and the ground-springs 21 and 22. The closure of these last two springs places the so-called "ground-post" 33 in connection with ground-terminal G¹ through the

springs 21 and 22 and conductor 281. The calling subscriber then proceeds by pressing the push-button 27 four times. The spring 29, each time the button is pressed, 5 breaks connection with contact-point 31 and closes with the ground-post 33. In this way, the "vertical-line-conductor" 34 is grounded four times in succession, thereby energizing the "vertical-line-relay" 40 of the 10 "first-selector" B. The path of the energizing current may be traced from ground G¹ at the sub-station A through springs 21 and 22, conductor 281, ground-post 33, spring 29, "vertical-line-conductor" 34, conductor 283, "vertical-line-relay" 40, "line-switching-relay-springs" 173 and 174, conductor 284, conductor 285 to the non-grounded terminal of battery B¹ and to ground G. Being energized, the "vertical-line-relay" of the "first-selector" B attracts its armature 42 four times and grounds the spring 44 with the spring 45 four times in succession. The result is that the "vertical-magnet" 47 is energized four times, the 15 current passing from ground G² to springs 45 and 44, through conductor 286, "private-springs" 98 and 97, conductor 287, "side-switch-wiper" 117, conductor 288, "vertical-magnet-coils" 48 and 49, conductors 289 and 285 to the non-grounded terminal of battery B¹ and to ground G. Each time the "vertical-magnet" is energized, the shaft is raised one step in a manner that has already been described; so that by four pulsations 20 of the "vertical-magnet," the shaft is raised four times, and the "line" and "private" wipers are thereby raised to the fourth level and placed opposite the first contact of the fourth row of their respective banks of contacts. At the first step, the "normal-spring" 154 separates from contact-point 155 and engages, instead, with the contact-point 156 which is connected with ground at G³. A guarding potential is, therefore, established 25 at the "connector - private - bank - contacts" corresponding to the number 500, which latter is supposed to be the number of the sub-station A. The path by which this guarding potential is transmitted, may be traced from ground G³ through "line-switching-relay-springs" 167 and 168, conductor 290, contact-point 156, "normal-spring" 154, conductor 291, "private-normal-springs" 162 and 163, and conductor 30 50 55 60 65 70 75 80 85 90 95 100 105 110 115 120 125 130

408 which constitutes the "private-normal-trunk-conductor" that leads directly to the "connector-private-banks." It is evident that this guarding potential will remain on this line until the switch is released. Therefore, no subscriber may call this number until after he, the calling subscriber, is through. At the next step the calling subscriber presses the button 28 once. Spring 30 breaks from contact-point 32 and comes 65 in contact, momentarily, with the ground- post 33. The result now is that the "rotary-line-relay" 41 at the "first-selector" B is energized once. The energizing circuit is from ground G¹ at sub-station A to ground-post 33, through spring 30, "rotary-line-conductor" 35, conductor 292, "rotary-line-relay" 41, conductor 314, springs 172, 173 and 174, and conductors 284 and 285 to the non-grounded terminal of battery B¹ and to ground G. When the "rotary-line-relay" 41 is energized, the "rotary-line-relay-armature" 43 is attracted once, causing spring 46 to be grounded by coming in contact with spring 45. A circuit is thereby closed through the "private-magnet" 90, which may be traced from ground G² through springs 45 and 46, conductor 293, "private-magnet" 90, conductors 294, 295, 289 and 285 to the non-grounded terminal of battery B¹ and to ground G. The "private-magnet" 90 is thus energized once, and its armature 91, by a downward and then a returned stroke to normal position, allows the "side-switch-finger" 108 to pass from behind the rear-most escapement-tooth 104 of the lower escapement-spring 101, to the rear of the forward tooth of the same spring. The "side-switch-finger" 108, however, does not quite strike the front tooth 105, but is prevented from doing this by the lug 110 on the "side-switch-arm" 109, which comes in contact with the cam 145. As soon as the "side-switch" is drawn to the second position, the "side-switch-wiper" 116 closes connection with contact 122, and a circuit is thereby closed through the "rotary-magnet" 60, energizing the same, and bringing about the rotation of the shaft.

The energizing circuit through the "rotary-magnet", beginning with ground G⁴, extends through contact-point 122, "side-switch-wiper" 116, conductor 296, interrupter-springs 69 and 68, "rotary-magnet" 60, conductors 295, 289 and 285 to the non-grounded terminal of battery B¹ and to ground G. As soon as the "rotary-armature" 63 is attracted, the "rotary-pawl" 72 engages with the longitudinal teeth 144, and the shaft is rotated one step. The "private-wiper" 149 then engages with the first contact of the fourth row of the "private-bank" 150, and the "line-wipers" 147 and 146 engage respectively with the "vertical" and the "rotary" contact-points of the first contact-terminal of the fourth row of the "line-bank" 148. As soon as the shaft is rotated, the cam 145 disengages from the lug 110 on the "side-switch-arm" 109, and the "side-switch-arm-finger" 108 falls against the rear edge of the front tooth 105 of the lower escapement-spring 101, merely to rest there a short time. The "rotary-armature-finger" 70, being carried by the "rotary-armature", depresses the "private-magnet-armature" 91, and immediately the "side-switch-arm-fin- 130

ger" 108 disengages from the escapement-tooth 105. As soon as said tooth is disengaged or cleared, the retracting-spring 137 draws the "side-switch-arm" forward, so that 5 the finger 108 falls in turn against the rear of the upper front tooth 103. Immediately after the "rotary-armature" 63 strikes the "rotary-magnet-pole-piece", the interrupter-finger 67 is instrumental in opening the energizing circuit of the "rotary-magnet" at the 10 interrupter-springs 68 and 69. As soon as the energizing current ceases to flow in said circuit, the "rotary-armature-retracting-spring" 66 draws the "rotary-armature" back 15 to its normal position. But, as the "rotary-armature-finger" 70 begins to fall back, the "private-magnet-armature" 91 follows, and before the interrupter-springs 68 and 69 have had time to re-engage, the "side-switch-arm-finger" 108 clears the upper forward escapement-tooth 103, and the "side-switch" falls to the third position against the "side-switch-stop" 136. When the "side-switch" 20 passes from the second to the third position, the "side-switch-wiper" 116 is then carried from engagement with the contact-point 122 into engagement with contact-point 123. By the time the interrupter-finger 67 permits the interrupter-springs to close contact, the 25 circuit through the "rotary-magnet" is broken from ground at said "side-switch-wiper". In the third position of the "side-switch", the "vertical" and "rotary" line-side-switch-wipers 119 and 120 are respectively engaged with the contact-points 132 and 135. It is evident that the line-conductors 34 and 35, at the end of the operation just described, are extended to the terminals 30 of the "line-bank" 148, by way of the "line-wipers" 146 and 147 and thence to an idle "connector" C¹⁰ (Fig. 2) that would be situated opposite the bank-contacts c¹, by way of trunk-line-conductors similar to trunk-conductors 297 and 298. Said "connector" 40 has control of a ringer-generator that produces current of such frequency, for example, that only the bells of substation No. 410 will respond. It has been pointed out that "connectors" of the four-hundred or C- 45 group, Fig. 2, fall under this type and draw ringing current from the generator D. A guarding potential is established at the first contact of the fourth row of the "private-bank" 150 when the "private-side-switch-wiper" 118 engages with the contact-point 129. This guarding potential exists by reason of a circuit which puts said "private-contact-point" in connection with the grounded terminal of the battery B¹ through the 50 ground G⁵ at the "side-switch", contact-point 129, "private-side-switch-wiper" 118, conductor 299, and "private-wiper" 149 to the "private-contact-point" with which it is engaged. Had the trunk-conductors leading 55 from the first contact of the fourth row of the "line-bank" 148 been occupied by some other "first-selector", the "line-wipers" 147 and 146 would not have been able to retain connection with said trunk-conductors. Had such been the case—and not only the first contact of the fourth row, but also the next succeeding eight been occupied—the first nine contacts of the fourth level of the "private-bank" 150 would have been supplied with a guarding potential. A guarding potential would have been provided at each individual "private-contact-point" in the same manner that was described in connection with the first contact-point. Under these 60 conditions, if the calling subscriber energizes the "private-magnet" 90 once, by once pressing button 28, he causes the "side-switch" to pass from the first to the second position; and the "rotary-magnet" 60 will be energized the instant that the "side-switch-wiper" 116 closes with contact-point 122. The shaft 140 is rotated one step by the "rotary-pawl" 72, and the wipers are switched into conjunction with the first contacts of the fourth levels of their respective banks. 65 With the difference, however, that at the instant that the "private-wiper" 149 closes with the first contact of the fourth level of the "private-bank", a circuit is closed through the "private-magnet" 90. Battery 70 current energizes said "private-magnet" in its passage from the grounded terminal G of battery B¹ through an occupying switch and circuit not shown; through the first contact of the fourth level of the "private-bank", 75 thence through the "private-wiper" 149, conductor 299, "private-wiper" 118, contact-point 128, conductor 300, "private-magnet" 90, and through conductors 294, 295, 289 and 285 to the non-grounded terminal of battery 80 B¹. The "private-armature" 91 is then retained by magnetic force against the "private-magnet-pole-piece", and the "side-switch" is detained in its second position 85 with the "side-switch-finger" 108 resting on 90 the rear edge of the upper front escapement-tooth 103. The energizing circuit through the "rotary-magnet" will be opened immediately after the "rotary-armature" strikes the "rotary-magnet-pole-piece", as before, and 95 the "rotary-armature" then returns to its normal position; but the "private-armature" does not follow as it did in the last case. The circuit through the "rotary-magnet" is closed again as soon as the interrupter-springs 100 re-engage; and the "rotary-armature" is attracted once, rotating the shaft to the second contacts; but the "private-magnet" still remains energized, owing to the 105 guarding potential at the second "private-contact-point". Again the "rotary-armature" breaks the circuit through the "rotary-magnet", and its armature returns to its normal position. These automatic operations 110 are repeated as often as the "private-wiper" 130

149 continues to encounter busy contact-points. After the shaft is rotated nine steps, and the "private-wiper" is engaged with the ninth "private-contact" of the fourth level, 5 the "rotary-magnet" is then energized once more, and the "rotary-pawl" 72 rotates the shaft one more step. As soon as the "private-wiper" leaves the ninth "private-contact-point", the circuit through the "private-magnet" 90 is then broken. The "private-armature" 91 is then restored to the care of the "rotary-armature-finger" 70 which, at 10 this time, is drawn toward the "private-magnet-pole-piece." But, immediately after the shaft is locked with the wipers on the tenth contacts, the circuit through the "rotary-magnet" is opened, and the "private-armature" follows the "rotary-armature" to normal position. The "side-switch" then passes 15 to the third position, as in the first case, before the interrupter-springs re-engage. The "line-conductors" 34 and 35 are now extended to a "connector" over the trunk-line-conductors 297 and 298 which lead from the 20 tenth contact of the fourth level of the "line-bank" 148. This "connector" is represented at C¹⁰, Fig. 2. As soon as the "private-side-switch-wiper" 118 closes with the contact-point 129, a guarding potential is thereby 25 established at the tenth "private-contact" of the fourth level so as to protect the trunk-line just occupied against intrusion. The subscriber's next operation is to press the button 27 once, this act corresponding to the 30 second digit of the number 410. The "vertical-line-conductor" 34 is thereby grounded at the ground-post 33, as it was in the first instance, with the result that the "vertical-line-relay" at the "connector" C¹⁰ is energized. 35 The circuit, in this instance, passes from ground G¹ to the "vertical-line-conductor" 34 through the "vertical-side-switch-wiper" 119, contact-point 132, conductor 301 and "vertical-line-wiper" 147, "vertical-trunk-conductor" 297, "vertical-line-relay" 200, conductors 302, 303, 304 and 305 to the 40 non-grounded terminal of battery B¹ and to ground G. The armature 201 of the "vertical-line-relay" 200, upon being attracted, 45 closes a circuit through the "vertical-magnet" 207 from ground G² through springs 205 and 206, conductor 306, "private-springs" 218 and 217, conductor 307, "side-switch-wiper" 237, conductor 308, "vertical-magnet" 207, conductors 303, 304 and 305 to the 50 non-grounded terminal of battery B¹ and to ground G. The "vertical-magnet" 207, upon being energized but once in this manner, raises the shaft 234 one step by 55 means of the "vertical-pawl" 211, as was shown in connection with the "first-selector". The wipers are thereby brought to a level with the first row of their respective banks, just opposite the first contact-terminals. At 60 65 the same time that the "vertical-line-relay"

200 of the "connector" C¹⁰ is energized, the "vertical-line-relay" 40 of the "first-selector" B is also energized; but the "side-switch-wiper" 117 of said "first-selector" not being in contact with the first "side-switch-contact-point" 124, the energization of said "first-selector-vertical-line-relay" has no significance at this stage. The calling subscriber next presses the button 28 once and thereby energizes the "rotary-line-relay" 202 at the "connector" C¹⁰ through a circuit as follows: from ground G¹ of sub-station A to ground-post 33, through spring 30, "rotary-line-conductor" 35, "rotary-side-switch-wiper" 120, contact-point 135, conductor 309, "line-switching-relay-springs" 171 and 170, conductor 310, "rotary-line-wiper" 146, "rotary-trunk-conductor" 298, "rotary-line-relay" 202 of "connector" C¹⁰, conductors 335, 302, 303, 304 and 305 to the non-grounded 85 terminal of battery B¹ and to ground G.

The "rotary-line-relay," upon attracting its armature 203, closes the "line-relay-springs" 204 and 205 together, thereby energizing the "private-magnet" 216. The current passes from ground G² to the "line-relay-springs" 205 and 204, conductor 312, "private-magnet" 216, conductor 305 to the non-grounded terminal of battery B¹ and to ground G. The "private-magnet" thus being energized once, attracts its armature once, and the "connector-side-switch" passes from the first to the second position in the same manner that the "first-selector-side-switch" did when the "first-selector-private-magnet" was first energized. The "side-switch-arm-finger" 243 at the downward stroke of the "private-armature" 222 leaves the lower escapement-tooth 226 and is caught by the escapement-tooth 224 just above; and on the returned stroke of the said "private-armature" the "side-switch-arm" passes to a position behind the front lower escapement-tooth 227. The same ground impulse or momentary closure of the circuit that operates the "rotary-line-relay" 202 of the "connector" C¹⁰ also energizes the "rotary-line-relay" 41 of the "first-selector" B, as well as the "normal-cut-off-relay" 160. But the operations of these last two relays of the "first-selector" B are of no effect, at present. The energizing circuit through the "rotary-line-relay" 41 has already been pointed out. The energizing circuit through the "normal-cut-off-relay" 160 is as follows: from ground G¹ at sub-station A over the "rotary-trunk-conductor" 35 through the "rotary-side-switch-wiper" 120, conductor 309, springs 171 and 170, conductor 313, "private-normal-relay" 160, conductor 314, springs 172, 173 and 174, conductors 284 and 285 to the non-grounded terminal of battery B¹ and to ground G. At the next operation, the calling subscriber presses button 27 ten times, this switching 130

operation corresponding to the last digit of the number to be called. The "vertical-line-conductor" 34 being grounded ten times, the "vertical-line-relay" 200 of the "connector" C¹⁰ operates its armature 201 ten times. The energizing circuit through this relay has already been traced. The "vertical-line-relay-armature" 201, in bringing the springs 205 and 206 together, closes a circuit through the "rotary-magnet" 213 each time. This circuit begins at ground G⁶ and extends through "line-relay-springs" 205 and 206, conductor 306, "private-springs" 218 and 217, conductor 307, "side-switch-wiper" 237, conductor 315, "rotary-magnet" 213, and conductors 304 and 305 to the non-grounded terminal of battery B¹ and to ground G. Each time the "rotary-magnet" is energized, the "rotary-armature" 212 is attracted, and the shaft is rotated one step, so that the subscriber, by pressing the button 27 ten times, rotates the shaft 234 ten steps or places. At the tenth step, the "private" and "line" wipers will be found in contact with the tenth contact-terminal of the first level of their respective banks. The "line-wipers" 246 and 247 are then in connection with the line of subscriber No. 410, which latter terminates at the tenth terminal of the first level of the "line-bank" 248. But as the "side-switch" is still in the second position, the calling subscriber is not yet in direct connection with the desired line. It is necessary for the "side-switch-wipers" 239 and 240 to pass from their second position to the third position into connection with contact-points 317 and 316, respectively, at which time the circuit will be completed over the conductors 318 and 319 which connect said points with the "line-wipers." In the next operation, the calling subscriber presses the button 28 once and for the last time. The "rotary-line-conductor" 35 is now grounded once, and the "rotary-line-relay" 202 at the "connector" C¹⁰ attracts its armature once. The "private-magnet" 216 is again energized once, and its armature 222 is attracted. The front tooth 227 on the lower escapement-spring then clears or disengages the "side-switch-arm-finger" 243, at which instant the "side-switch" springs into its third position before the "private-armature" returns to its normal position. After the connection is completed, the signaling-button 23 at sub-station A is pressed. The "vertical-line-relay" 200, at the "connector" C¹⁰, is thereby energized by a current passing from ground G¹ at sub-station A through springs 21 and 22, contact-point 26, spring 24, thence through springs 19 and 20, contact-point 31, "vertical-line-relay" 200 to the non-grounded terminal of battery B¹ and to ground G. When the "vertical-line-relay" is thus energized at this time, and the "line-relay-springs" 205 and 206 are brought into contact, the ringer-relay 268 is in turn energized through a circuit as follows: from ground G⁶ through springs 205 and 206, conductor 306, springs 218 and 217, conductor 307, "side-switch-wiper" 237, contact-point 331, ringer-relay 268, conductors 332, 333, 334, 335, 302, 303, 304 and 305 to the non-grounded terminal of battery B¹ and to ground G. When the ringer-relay is energized, the ringer-springs 271 and 274, which constitute the terminals of the called subscriber's line, are closed respectively with the ringer-relay-springs 272 and 275. An alternating current is then projected on the "normal-trunk-conductors" 329 and 330 and thence to the line-conductors across which is located the sub-station desired, in this case sub-station No. 410. This alternating current is, for example, of such a nature that, although it passes through all the ringers that are bridged across the line-conductors 199 and 282, only the ringer 336 at sub-station No. 410 responds. The path of the ringing current through the bell or ringer 336 is from generator D through ringer-relay-springs 275 and 274, "side-switch-wiper" 240, contact-point 316, conductor 319, "rotary-line-wiper" 246, "rotary-trunk-conductor" 330, "rotary-line-conductor" 282, spring 337, contact-point 338, conductor 339, condenser 340, ringer 336, ringer-spring 341, switch-hook 342, conductor 343, contact-point 344, spring 345, "vertical-line-conductor" 199, "vertical-normal-conductor" 329, "vertical-line-wiper" 247, conductor 318, contact-point 317, "side-switch-wiper" 239, and ringer-relay-springs 271 and 272 to generator D. The subscriber at sub-station No. 410, upon hearing the bell ring, will remove the receiver from its hook, thus breaking the ringing circuit between the hook 342 and the spring 341 and closing contact between the secondary springs 346 and 347, and between the local springs 348 and 349 and the ground-springs 350 and 351. The calling subscriber, upon releasing the signaling-button, restores the "vertical-line-relay" 200 and the ringer-relay 268 of the "connector" C¹⁰, so that the circuit from sub-station No. 500 to substation No. 410 is completed from the receiver 8 through conductor 352, secondary winding 16 of induction-coil 12, contact-point 25, spring 24, thence to springs 19 and 20, contact-point 31, spring 29, "vertical-line-conductor" 34, "side-switch-wiper" 119 of the "first-selector" B, contact-point 132, conductor 301, "vertical-line-wiper" 147, trunk-conductor 297, condenser 354 of "connector" C¹⁰, conductor 355, ringer-relay-springs 270 and 271, "side-switch-wiper" 239, contact-point 317, conductor 318, "vertical-wiper" 247, "normal-conductor" 329, line-conductor 199, spring 345, contact-point 344, conductor 343, 130

secondary springs 346 and 347, conductor 356, push-button-spring 357, contact-point 358, secondary winding 359 of induction-coil 360, conductor 361, receiver 362, conductor 363, contact-point 388, spring 387, "rotary-line-conductor" 282, "normal-conductor" 330, "rotary-line-wiper" 246 of "connector" C¹⁰, conductor 319, contact-point 316, "side-switch-wiper" 240, springs 274 and 273, conductor 364, condenser 365, trunk-conductor 298, "rotary-line-wiper" 146 of the "first-selector" B, conductor 310, "line-switching-relay-springs" 170 and 171, conductor 309, contact-point 135, "side-switch-wiper" 120, "rotary-line-conductor" 35, spring 30, contact-point 32, conductor 366, and back to receiver 8. The two subscribers are now ready to converse, and when the subscriber at sub-station No. 410 speaks in the transmitter 367, in a manner well-known, and through the means of a battery 368 and the induction-coil 360, the electric pulsations corresponding to the sound waves that are received in the transmitter are induced or repeated into the secondary winding 359 of the induction-coil. This induction-coil has been described in the circuit with the receiver 8 at sub-station A, so that when the subscriber at sub-station No. 410 talks into his transmitter, the subscriber at sub-station A is able to hear what is said at that station. Similarly, when the subscriber at sub-station A talks into his transmitter 11, electric pulsations are induced in the secondary winding 16 of the induction-coil 12; and said coil being in series with the receiver 362 at sub-station No. 410, the called subscriber is able to hear the conversation from said sub-station A. When the conversation is over, the switches may all be released by the calling subscriber, if he presses the buttons 27 and 28 simultaneously. The "rotary" and "vertical" line-conductors 35 and 34 are then grounded at the same time, for a moment. As soon as the "rotary-line-conductor" 35 is grounded, the "rotary-line-relay" of the "first-selector" B is energized (as it always is when the "rotary-line-conductor" is grounded), and the "rotary-line-relay" of the "connector" C¹⁰ is also energized. The energization of the former relay causes the "private-magnet" 90 to be energized, as in cases previously described. This causes the "private-spring" 98 to separate from the "private-spring" 97 and close with "private-spring" 99. In the "connector," also, the magnetization of the "rotary-line-relay" causes the "private-magnet" to attract its armature, as in other cases, separating the "private-springs" 217 and 218, and causing the latter to engage with the "private-spring" 219, as well as with "private-spring" 220—with the last one incidentally. Now, as soon as the "vertical-line-conductor" 34 is connected

to ground, the "vertical-line-relay" 40 is energized, and the spring 44 is brought into engagement with the grounded spring 45, so that the three "line-relay-springs" are closed simultaneously.

As soon as the spring 44 touches the spring 45, the "release-magnet" 74 of the "first-selector" is energized through the following circuit: from ground G² through springs 45 and 44, conductor 286, "private-springs" 98 and 99, conductor 369, "release-magnet" 74, conductors 295, 289 and 285 to the non-grounded terminal of battery B¹ and to ground G. The "release-armature" 75 is then attracted, and the release-link 79 is so shifted that the aperture 80 in its forward end falls over the lug 82 of the "double-dog" and remains in that position as long as the springs 29 and 30 at sub-station A are kept on the ground-spring 33. At the same time, the "vertical-line-relay" at the "connector" C¹⁰ is energized, causing the "line-relay-springs" 206 and 205 to close in contact and to be retained so, together with the third "line-relay-spring" 204, as long as both line-conductors are kept grounded. At the instant that the springs 205 and 206 at the "connector" come into contact, the "release-magnet" 228 is energized through a circuit as follows: from ground G² through springs 205 and 206, conductor 306, "private-springs" 218 and 219, conductors 370 and 371, "release-magnet" 228, conductors 302, 303, 304 and 305 to the non-grounded terminal of battery B¹ and to ground G. As soon as the "release-magnet" attracts its armature 280, the locking-arms 232 and 233 of the "double-dog" 257 are drawn away from the ratchet-teeth on the shaft. The shaft, being left to the tension of the coil-spring 254, rotates in a backward direction upon the shaft-rest 253 until the "normal-arm" 256 meets the guide or normal-post 255. At that instant, the wipers clear the bank-terminals, the shaft-rest enters the channel 259 that traverses the circular ratchet-teeth, and the shaft of its own weight drops to its normal position. At the same time that the locking-arms are drawn away from the shaft-ratchet-teeth, the "side-switch-releasing-arm" 242 on the "double-dog", through the medium of the "side-switch-link" 372, rotates the "side-switch" about its pivots to the first position, locking the "side-switch-arm-finger" 243 behind the rearmost lower escapement-tooth of the escapement-spring 225. As soon as the "side-switch-wiper" 238 moves from engagement with the contact-point 373, the circuit through the "private-wiper" to ground is broken, and the guarding potential is removed from the tenth contact of the first level of the "private-bank". Therefore, the "line-switching-relay" of the "first-selector" K is also re-

stored to its normal position. As soon as the buttons at sub-station A are released, the energizing circuits through the "line-relays" of the "first-selector" and of the 5 "connector" are opened. These relays, upon being restored, break the circuit through the "release-magnet" of their respective switches, thus de-energizing them. As soon as the "release-magnet" of the "first-selector" 10 is de-energized, the "release-armature" is drawn back to its normal position by the retracting-spring that controls said "release-armature". The release-link, being attached to said armature, draws the 15 "double-dog-locking-arms" away from the shaft, which latter, being left to the influence of the coiled spring 151, is then restored to its normal position in the same manner as the "connector", and at the same 20 time that the "double-dog" is retracted by the release-link, the "side-switch" is restored to its normal condition. The "release-armature" of the "connector", when the "release-magnet" is de-energized, simply returns to 25 its normal position by reason of the tension of the retracting-spring 231. It was explained that the calling subscriber successfully made his connection with station No. 410; but had the line No. 410 been 30 busy when the "rotary-line-conductor" was grounded by the calling subscriber, after the "connector-wipers" had been rotated to the tenth contact of the first level, the connection would not have been completed. A 35 guarding potential would have been found at the tenth contact of the first level of the "private-bank" 250 and, therefore, said contact would have been connected directly to the grounded terminal of battery B¹, as in 40 other cases where guarding potentials have been described. Under such conditions, the "connector" is released upon the energizing of the "private-magnet" 216. The release mechanism is energized by the following 45 circuit: from ground-terminal G of battery B¹, through an occupying-switch and circuit (not shown) to the tenth "private-contact" of the first level of the "private-bank" 250, through the "private-wiper" 249, conductor 374, "private-side-switch-wiper" 238, contact-point 375, conductor 376, "private-springs" 220 and 219, conductors 370 and 371, "release-magnet" 228, conductors 302, 303, 304 and 305 to the non-grounded terminal 50 of battery B¹ and to ground G. The "private-springs" are so arranged that upon the downward stroke of the "private-armature" 222, when the "side-switch-finger" 243 is in the second position, the "private-springs" 219 and 220 are brought into contact; and it is through these that the "release-circuit" is completed if the called line 55 is busy. After attempting to make the connection, the calling subscriber presses his 60 signaling-button 23 and thereby grounds the "vertical-line-conductor" 34 from ground G¹ through springs 21 and 22, contact-point 26, spring 24, springs 19 and 20, contact-point 31, through spring 29. The "connector" being released, the effect of 65 grounding the "vertical-line-conductor", as described, is to raise the shaft 234 one step. As soon as the shaft is raised, the "normal-spring" 260 closes connection with the contact-point 261. The closing of these last 70 two conductors places the busy signaling-coil 279, Fig. 2, across the receiver 8 of the calling subscriber. This busy circuit may be traced from said busy signaling-coil 279 through conductor 377, contact-point 261, 75 "normal-spring" 260, "side-switch-wiper" 239, ringer-relay-springs 271 and 270, conductor 355, condenser 354, "vertical-trunk-conductor" 297, "vertical-line-wiper" 147 of the "first-selector" B, conductor 301, contact-point 182, "side-switch-wiper" 119, 80 "vertical-line-conductor" 34, spring 29, contact-point 31, secondary winding 16 of induction-coil 12, conductor 352, receiver 8, conductor 366, contact-point 32, spring 30, 85 "rotary-line-conductor" 35, "side-switch-wiper" 120, contact-point 135, conductor 309, cut-off-relay-springs 171 and 170, conductor 310, "rotary-line-wiper" 146, "rotary-trunk-conductor" 298, "rotary-line-relay" 202, conductors 335, 302, 303, 304 and 90 305 back to the busy signaling-coil 278. The calling subscriber, on hearing the busy signal, and having been instructed on this point, understands that the number he is 95 trying to call is not accessible for the time being, and will restore the switches by pressing the buttons of the calling device simultaneously. When the subscriber presses both buttons, the "rotary" and the "vertical" line-conductors are simultaneously 100 grounded in the manner already described, and the "line-relays" of the "first-selector", and of the "connector", are simultaneously 105 magnetized. It has been shown that when 110 the "line-relays" of these switches are both energized at the same time, their "release-magnets" become energized. So it is evident that when the calling subscriber presses both buttons of the calling device at the 115 same time for a moment, the switching apparatus is fully released. The action of the switches during the release has already been explained. The only difference that will be noticed is that the shaft of the "connector" 120 being raised only, and the wipers not being engaged with the bank-terminals, drops straight down to its normal position when the "release-magnet" of the "connector" is energized. A line may be made busy in 125 several ways—when it is being used—first, by any of its members or subscribers calling a subscriber of any other line, and, second, it may be busy when one of its subscribers 130 is calling another subscriber on his own line,

or, third, when any other subscriber is calling said party-line. In the first case, a guarding potential is established at the "connector-private-banks" at the first vertical step of the "first-selector-shaft", as has been described in connection with the "first-selector" B, Fig. 1. In Fig. 3, for example, as soon as the shaft of the "first-selector" K is raised at the first step, the "normal-arm" 190 is removed from the "normal-spring" 191, and the latter, after breaking away from the contact-point 193, closes with contact-point 192. Each "private-contact-point" at the "connector-banks", Fig. 2, that corresponds to the number of the line which is calling, is then connected with ground over the "private-normal" that leads from said "first-selector" K to the "connectors". The circuit by which this connection is completed is as follows: from ground G⁸ at the "first-selector" K through springs 186 and 185, contact-point 192, "normal-spring" 191, "private-normal-relay-springs" 176 and 175, "private-normal-conductor" 378 to all "private-contact-points" connected with the cross-multiplying conductor 5. In the second case, the conditions for maintaining a guarding potential at the "private-contact-points" are not constant—that is, there are two phases; for when the "first-selector" is first operated, the conditions are the same; but after the connection has been completed, the connection to ground from the "private-contact" is then maintained through the "connector" that completes the operation. These operations will be described more fully hereinafter. In the third case, a guarding potential is communicated to the "private-banks" of the "connectors" only after the connection is completed, and it is through the "connector", as stated, that the same is furnished. This was clearly described when it was assumed that the "connector" C¹⁰ had connected the line of the calling subscriber at sub-station A with the tenth contact of the first row of the line-bank-terminal 248, Fig. 5. The "side-switch-wiper" 238 was brought into the third position, in electrical connection with the contact-point 373, and the guarding potential was established at the tenth contact of the first level of the "private-bank" 250.

The "private-contact-point" is clearly shown in engagement with the "private-side-switch-wiper" 238 of "connector" C¹⁰, Fig. 2; and the connection with ground is maintained from ground G⁷ at "connector" C¹⁰, through contact-point 373, "private-side-switch-wiper" 238, conductor 374, to "private-wiper" 249 to the tenth contact of the first level of the "private-bank" 250, and thence to all other "private-contacts" connected in multiple, such, for instance, as those connected with the conductors 2, 379,

380 and 381 and cross-multiplied by conductor 5. As soon as the "private-side-switch-wiper" 238 comes in contact with contact-point 373, after the "rotary" and "vertical" "line-wipers" engage with the tenth contacts of the first level of the "line-bank" 248, the "line-switching-relay" 177 of the "first-selector" K, Fig. 3, is then energized by a current that passes from ground G⁷ at "connector" C¹⁰, Fig. 2, through "private-side-switch-wiper" 238, conductor 374, "private-wiper" 249, cross-multipling-conductor 5, through "private-normal-conductor" 378, "private-normal-springs" 175 and 176, thence through "normal-spring" 191 and contact-point 193, and "line-switching-relay-coil" 177 to the non-grounded terminal of battery B¹ and to ground G. As soon as the "line-switching-relay" is energized, its armature 178, upon being attracted, causes the "line-switching-relay-springs" 179, 180 and 181 to separate from each other, thereby opening a bridge across the "normal-conductors" 329 and 330, which is normally closed through the "vertical" and "rotary" "line-relays" 59 and 107, and through the "line-switching-relay-springs" 180 and 181. Two other springs 182 and 183 are also separated, but this separation has no function at the present time. Also, the spring 185 is pulled away from spring 186 and brought into contact with spring 184. The change in position of these last three springs has no significance at present. The object in removing the normally bridged "vertical" and "rotary" "line-relays" 59 and 107 is two-fold. First, to prevent talking currents from being side tracked, and, second, to prevent any accidental operation of the mechanical parts of the "first-selector" by the signaling current that is projected by the calling "connector" over the "normal-line-conductors" 329 and 330. It is evident that when one line is connected with another, the called line is not able to call as long as a "connector" is set-on or occupies the said line, because the called subscriber's "line-relays" are out of action. As long as these relays are retained out of operation, the "first-selector" K may not be used for calling. Provision has been made, therefore, so that if the calling subscriber neglects to restore the switches, and leaves the "connector" on the line, said called subscriber may himself release the said "connector". Assuming that the "connector" C¹⁰, Fig. 2, is situated across the "normal-conductors" that lead to the "first-selector" K, Fig. 3, and if the subscriber at sub-station No. 410 presses the buttons 382 and 383 of his calling device simultaneously, the "rotary" and "vertical" line-conductors 282 and 199 will be simultaneously grounded and the "back-release-relays" 263 and 262 of the "connector" C¹⁰ will be energized at the

same time. The "connector-release-magnet" will then become magnetized through a circuit from ground G^s through springs 266 and 267, conductors 384 and 371, "release-magnet" 228 to the non-grounded terminal of battery B^s and to ground G . The release of the "connector" then results, as previously described. At the instant that the "side-switch-wiper" 238 breaks away from the contact-point 373, the circuit through the bridge-cut-off-relay 177 is broken, and the bridge-cut-off-relay-springs are restored to their normal positions, among them springs 179, 180 and 181. The sub-station No. 410, or any other sub-station on the same line, after this restoration, is able to make a call. In this system, if a subscriber on a party-line wishes to call another subscriber on the same line, he may do so. The circuits and mechanisms involved in such a case are shown in Fig. 6, in which K represents the "first-selector" and C^{10} the "connector" in use, and the sub-stations Nos. 110, 210, 310 and 410 are distributed along the "vertical" and "rotary" line-conductors 199 and 282. Should the subscriber No. 110 wish to call the subscriber No. 410, on the same line, he (the calling subscriber) will proceed in the same manner described in connection with the subscriber of sub-station A, Fig. 1. When he removes his receiver 385 from the switch-hook 386, the hook rises and the secondary springs 387 and 388 will close contact, as will also the local springs 389 and 390 and the ground-springs 391 and 392. The circuit conditions thus brought about are the same as in sub-station A, or any other sub-station in this system, when the receiver is removed from its hook. The calling device controlled by the push-buttons 393 and 394 is operated, as before described, during the calling of sub-station No. 410. With respect to the first digit, the push-button 393 is pressed four times, the "vertical-line-conductor" 199 is grounded four times, and the "first-selector-shaft" is raised to the fourth level. Then, when the "rotary-line-conductor" 282 is grounded once at the time that the push-button 394 is pressed once, the wipers 396 and 397 are rotated into connection with some idle trunk leading to some idle "connector". It is assumed that the idle trunk selected leads to the "connector" C^{10} . At the first vertical step of the shaft of the "first-selector" K , a guarding potential is established at the "connector-private-banks", as usual. The circuit in this case is from ground G^s through "private-bridge-cut-off-springs" 186 and 185, contact-point 193, "normal-spring" 191, "private-normal-springs" 176 and 175, "private-trunk-conductor" 378 to the tenth contact of the fourth level of the "private-banks" of the "connectors" of the one, two, three and four-

hundred group, as clearly shown in Fig. 2. After the operation of the calling device, corresponding to the digit four, a circuit from sub-station No. 110 is extended to the "connector" C^{10} over the "vertical-line-conductor" 199, "side-switch-wiper" 195, conductor 395, "vertical-line-wiper" 396, "vertical-trunk-conductor" 297, through the "connector" and back over the "rotary-trunk-conductor" 298, "rotary-line-wiper" 397, conductor 398, bridge-cut-off-relay-springs 183 and 182, "side-switch-wiper" 194, and back over the "rotary-line-conductor" 282. The shaft of the "connector" C^{10} , upon the operation of the calling device for the second digit, is raised to the first level, and the "side-switch" is thrown into the second position. Upon the grounding of the "vertical-line-conductor" 199 ten times, corresponding to the last digit, the wipers are rotated into engagement with the tenth contact of the first level of their respective banks. It will be borne in mind that said contacts are the "normal-terminals" of the line which is calling, and that a guarding potential was established over the "private-normal" 378 when the "first-selector" K was operated. In other words, the calling subscriber is now calling his own line. Ordinarily, upon the grounding of the "rotary-line-conductor", when the "side-switch" of the calling "connector" is in the second position, and the number called is busy, the calling "connector" is released. Such a result should be anticipated then at the next step of the calling subscriber; but it will be remembered that attention was called to the fact that every time the "rotary-line-conductor" is grounded, the "private-normal-relay" 157 is energized. Then if the button 394 is pressed, when this relay attracts its armature 158, the "private-normal-relay-spring" 175 is separated from spring 176 and closed with spring 159. Whenever this occurs, after the "normal-spring" 191 has closed with contact-point 193, the guarding potential established at the "connector-private-banks" over the "private-normal-trunk" 378 is removed. It will be understood that when the push-button 394 is pressed for the last time, and the "rotary-trunk-conductor" 282 is grounded once, the "private-magnet" 216 of "connector" C^{10} , Fig. 6, will then be magnetized once, and the "private-armature" will be drawn down once and then released. Upon the downward stroke of the "private-magnet-armature" 222, the "private-springs" 218 and 219 are brought into contact in a manner already described; but the "connector" is not released, because at the same time that the "private-magnet" is energized the "private-normal-relay" 157 of the "first-selector" K removes the guarding potential, as described. The energizing circuit through the

"private-normal-relay" is from ground G¹¹ at sub-station No. 110 over the "rotary-line-conductor" 282, through "side-switch-wiper" 194, bridge-cut-off-relay-springs 182 and 183, "private-normal-relay" 157, bridge-cut-off-relay-springs 181, 180 and 179 to the non-grounded terminal of battery B¹ to ground G. Upon the downward stroke of the "private-magnet-armature" 222, Fig. 5, 10 the "side-switch" passes to the third position, and the "private-normal-relay" 157 is energized. At once, a guarding potential is established again at the "private-contact" with which the "connector-private-wiper" 15 249 is engaged; but this time it comes from an opposite direction. Said "private-wiper" is connected to ground over conductor 374, "side-switch-wiper" 238, contact-point 373 to ground G⁷. At the instant that this connection to ground is closed, the bridge-cut-off-relay 177 of the "first-selector" K is energized through the following circuit: from ground G⁷ through contact-point 373, "side-switch-wiper" 238, conductor 374, "private-wiper" 249, through the tenth contact of the 20 first level of the "private-bank" over the "normal-trunk-conductor" 378, through "normal-relay-springs" 175 and 159, bridge-cut-off-relay 177 to the non-grounded terminal of 25 battery B¹ and to ground G. Immediately, the bridge-cut-off-relay-springs 179, 180 and 181 are separated, as well as springs 182 and 183. The spring 185, after 30 breaking contact with spring 186, closes in 35 turn with spring 184.

As soon as the first three springs 179, 180 and 181 break contact, the energizing circuit through the "private-normal-relay" 157 is opened, and the armature 158 begins to 40 return to its normal position. The "private-normal-relay-springs" 159, 175 and 176 are so adjusted with respect to each other that for a given length of time they are simultaneously in contact. For instance, when 45 the armature 158 loses control over said springs, the middle spring 175 begins to travel in the direction of spring 176, the spring 159 follows for a short distance, and it is not until after the spring 175 meets the 50 spring 176 that spring 175 breaks from spring 159. Thus the continuity of the energizing circuit through the bridge-cut-off-relay 177 is not interrupted at this point, after the energizing circuit has been established through the latter relay. At the time 55 that the bridge-cut-off-relay is energized, and the relation of the springs it controls is changed, the circuit through said cut-off-relay is very quickly changed, and for a moment the circuit through said relay is interrupted, but the interruption is of such short duration that the armature 178 does not have time to move from the pole-piece of 60 said relay. Since the "private-normal-relay-springs" 159, 175 and 176 come together for

a time, not only when the "private-normal-relay" 157 is de-energized, but also when it is energized, it may appear that as a result the bridge-cut-off-relay 177 will also be operated each time, correspondingly, by the 70 closing of a circuit that passes from ground G⁸ through bridge-cut-off-relay-springs 186 and 185, thence through contact-point 193, normal-spring 191, "private-normal-springs" 176, 175 and 159, through bridge-cut-off-relay 177, through battery B and to ground G. Although a current does pass through the 75 said bridge-cut-off-relay at such a time, the duration of the circuit is for a very short time only, since the armature 158 travels 80 very quickly when attracted, and therefore the armature 178 of the bridge-cut-off-relay does not have time to become operative. The energizing circuit through the bridge-cut-off-relay, after the "normal-relay" is de-energized, is as follows: from ground G⁷ through contact-point 373, "side-switch-wiper" 238, conductor 374, "private-wiper" 249, "private-normal-trunk-conductor" 378, "private-normal-relay-springs" 175 and 176, "normal-spring" 191, contact-point 193, bridge-cut-off-relay-springs 185 and 184, bridge-cut-off-relay 177 to the non-grounded terminal of 90 battery B¹ and to ground G. The circuit, instead of including the "normal-relay-spring" 95 159, includes the "normal-relay-spring" 176, the "normal-spring" 191, contact-point 193, and the bridge-cut-off-relay-springs 185 and 184. Consequently, the guarding potential 100 that prevents any other line from seizing the line that leads to the sub-stations Nos. 110, 210, 310 and 410 also retains the bridge-cut-off-relay 177 and its energized condition. The object in opening up the bridge-relay-springs 179, 180 and 181 has once been stated, 105 and is to open up the bridge across the line-conductors 282 and 199, formed by the "vertical" and "rotary" "line-relays" 59 and 107 through the springs 180 and 181, for two purposes: first, to prevent the ringing-current projected over said line-conductors from interfering with the mechanisms of the switch, and, second, to avoid any useless 110 interception of voice-currents when subscribers are communicating. The next two springs 182 and 183 are so separated that the ringing-current cannot release the "connector-switch" by the energization of the "connector-line-relays" 200 and 202. The path of this ringing current, if such were 115 possible, would be from the "side-switch-wiper" 194 through the two springs 182 and 183, "rotary-line-wiper" 397, trunk-conductor 298, "rotary-line-relay" 202, "vertical-line-relay" 200, "vertical-trunk-conductor" 297, "vertical-line-wiper" 396, conductor 395, and to "side-switch-wiper" 195. Even after 120 the said springs 182 and 183 are separated, however, a path for the ringing current through the "connector-rotary-line-relay" 125 130

still remains; but the said remaining circuit includes the "first-selector-rotary-line-relay," the "private-normal-relay," the "connector-rotary-line-relay," and the "connector-5 tor-vertical-line-relay" in series. Said circuit is of such high resistance that the current admitted is too weak to operatively energize the aforesaid relays. Said circuit may be traced as follows: from the "normal-conductor" 330 through the "first-selector-rotary-line-relay" 107, thence through the "private-normal-relay" 157, "rotary-line-wiper" 397, trunk-conductor 298, the "connector-rotary-line-relay" 202 and the "vertical-line-relay" 200, the "normal-trunk-conductor" 297, wiper 396, conductor 395, "side-switch-wiper" 195 to the "normal-trunk-conductor" 329. After the calling subscriber has established connection, he presses his 10 signaling-button and grounds the "vertical-line-conductor" 199 with the result that the ringer-relay 268 is energized. The steps leading to such energization have already been described. The ringer-relay, upon being 15 energized, and by its armature, forces the ringer-relay-springs 271 and 274 away from the springs 270 and 273, and then brings them in turn into connection with the springs 272 and 275, in the order named. The ringing current then passes from the ringer-generator D through ringer-relay-springs 272 and 271 over "side-switch-wiper" 240, "rotary-line-wiper" 246, "rotary-normal-conductor" 330, "rotary-line-conductor" 282, through the ringing devices of sub-stations Nos. 210, 310 and 410 and back over the "vertical-trunk-conductor" 199, "vertical-normal-conductor" 329, "vertical-line-wiper" 247, "side-switch-wiper" 239, ringer-relay-springs 274 and 275 to generator D. It has been explained that the ringing current of generator D will only operate the ringing apparatus of sub-station No. 410. The ringing current does not pass 20 through sub-station No. 110, because the circuit is open between the push-button-spring 399 and the contact-point 400. When the called subscriber responds by removing his receiver, the talking circuit then extends 25 through the receiver 362, conductor 361, secondary winding 359 of induction-coil 360, contact-point 358, spring 357, conductor 356, secondary springs 347 and 346, conductor 199, spring 401, contact-point 402, secondary springs 388 and 387, spring 399, contact-point 400, secondary winding 409 of induction-coil 403, receiver 385, contact-point 404, spring 405, "rotary-line-conductor" 282, contact-point 338, back to receiver 362. After 30 the conversation has terminated, either subscriber may release the switches by pressing both buttons of their respective calling devices at the same time. The "rotary" and "vertical" line-conductors being thus simultaneously grounded, the "connector" would 35 be released by the energization of the "back-release-relays" 262 and 263. The release-circuit on the vertical side is then from ground at the releasing sub-station and over the "vertical-line-conductor" 199, "vertical-normal-conductor" 329, "vertical-wiper" 247, "side-switch-wiper" 239, ringer-relay-springs 274 and 273, "back-release-relay" 262 to the non-grounded terminal of battery B¹ and to ground G. The release-circuit on the rotary side 40 extends from ground at said releasing station over the "rotary-line-conductor" 282, "rotary-trunk-conductor" 330, "rotary-line-wiper" 246, "side-switch-wiper" 240, ringer-relay-springs 271 and 270, and "back-release-magnet" 263 to the non-grounded terminal of battery B¹ and to ground G. In this way, the "release-magnet" of the "connector" is energized in a manner already described. The switch-shaft is restored to its normal 45 position, as well as the "side-switch." The energizing circuit through the bridge-cut-off-relay 177 is then broken, and the bridge-cut-off-relay-springs return to their normal positions. The springs 179, 180 and 181 are 50 restored to contact, and at once follows the de-energization of the "first-selector-line-relays" 59 and 107, resulting also in the restoration of the "first-selector." The release of these switches takes place during the momentary simultaneous grounding of both the line-conductors. When two subscribers on the same line are talking, if another subscriber on the same line desires to make a call, he removes his receiver from its hook, 55 which places his telephone across the line. He places the receiver to his ear before calling, and if voices are heard on the line he will know that the line is busy and will restore his receiver and wait until they are 60 through.

Reference was made, in connection with Fig. 3, to the "normal-conductor" of the "first-selector" K. In Fig. 1, the "normal-line-conductors" that connects the "first-selector" B with the "connector-banks" are indicated by the lines 406 and 407 and lead off from the "side-switch-wipers" 119 and 120, respectively. The "private-trunk-conductor" 408 is connected directly with the middle 65 spring 163 of the "private-normal-relay-springs." In Fig. 6, sub-stations Nos. 210 and 310 have their various parts situated similarly to the corresponding parts of sub-stations Nos. 410 and 110. In Fig. 3, the 70 same is true of these sub-stations; and although my invention has been described in connection with a very small number of lines, it is clear that it may be expanded into an automatic telephone system comprising a 75 central office with a multiplicity of subscribers' lines and trunk-lines, each of said subscribers' lines connecting one or more sub-stations with said central office, and each terminating in an individual step-by-step elec- 80

tro-magnetically-operated switching machine, substantially as described. Each of said individual switching machines may be operated by any subscriber of the corresponding line for the purpose of intercommunication along the said trunk-lines.

It is obvious that a "selector" of the character shown in Fig. 4—that is, one having provision for removing the guarding potential whenever the subscriber grounds the "rotary" side of his line—is really only necessary in connection with party-lines, it being possible to simply provide each party-line with a "selector" of this character, and 10 to then provide all other lines, or lines having but one station, with the ordinary or any suitable construction of "selector." As 15 a matter of convenience, however, and economy of insulation, etc., the entire exchange 20 may be equipped in the first instance with "first-selectors" of the character shown and described, whereby each subscriber's line is then ready for use as a party-line without any change whatever in the apparatus at the 25 central station, at least as far as the character and arrangement of the "first-selectors" is concerned. As illustrated, the said "selectors" are of the type shown and described in Patent No. 815,321, granted March 13, 30 1906, to Keith, Erickson and Erickson; but it will be understood that for the broader purposes of my invention they may be of any suitable, known or approved construction. Also, as illustrated, the "connectors" are of 35 the type shown and described in Patent No. 815,176, granted March 13, 1906, to Keith, Erickson and Erickson; but these particular switching machines may also be of any suitable, known or approved construction, as far 40 as the broader purposes of my invention are concerned. Again, the subscribers' apparatus or equipment may be of any suitable, known or approved character consistent with the different functions and results set forth 45 and the mode of operation hereinbefore described. If the "selector" signaling on a party-line is accomplished by the use of alternating ringing currents of different frequencies, the ringers or bells at the subscribers' stations on the party-line may then be 50 of the well-known harmonic or tuned character, such, for example, as those shown and described in an article entitled "Concerning harmonic party-lines," page 401 of the American Telephone Journal, June 17th, 1905. It will be understood, however, that I do not 55 limit myself to any particular form of apparatus. As illustrated, the "selectors" are of the well-known bridging type, inasmuch 60 as the "line-relays" of the "selector" must, in the absence of any other arrangement, be left across the "line-circuit" for the purpose of enabling the subscribers to release or restore the "selector" after they are through 65 talking. Also, as shown, local batteries are

provided at the subscribers' stations for the purpose of supplying the current necessary for talking purposes; but all current for switching and signaling purposes is supplied from the exchange or central station, batteries being employed for furnishing the current necessary for operating the switching machinery or apparatus, and dynamos or alternating-current-generators being employed at the central station for furnishing 70 the current necessary for ringing the bells at the subscribers' stations. As is claimed, the number of ringing-generators may correspond to the highest number of subscribers' stations on any one party-line; and if, for example, tuned bells or ringers are employed, the generator allotted to the party-line subscribers of a certain hundred can be capable of generating 75 a current of such frequency that it will 80 ring only the bells of these particular subscribers; the current from another generator allotted to another group of party-line subscribers can be capable of generating a current of such frequency that it will ring 85 the bells of this particular hundred group and no others; and the third and fourth generators can be adjusted accordingly. In 90 other words, each generator is common to all party-line subscribers, or to all subscribers 95 whose numbers belong to a certain hundred group, and is not used with respect to subscribers of other groups. In this way, each generator is individual to a certain group of subscribers, but is common to all of the subscribers in such group—that is, may be used 100 for ringing the bells at any of the subscribers' stations in the particular group to which it is allotted. Furthermore, it will be seen 105 that in each case the ringing current is supplied by any one of the generators which is controlled through the medium of a plurality of ringer-relays corresponding in number to the total number of "connectors" belonging to the group to which the said generator is allotted. With this arrangement, 110 each ringer-relay is individual to a certain "connector" and is only brought into use when that particular "connector" is employed by a calling subscriber for making 115 connection with some other line, or with his own line if he happen to be a party-line subscriber endeavoring to communicate with some other subscriber on the same line. When a party-line subscriber desires to communicate with some other subscriber on the same line, and is thereby compelled to call his own line, so to speak, the "connector" 120 which he employs for this purpose must be capable of making connection with the party-line regardless of the fact that, under ordinary conditions, and with the arrangements heretofore employed, this would be impossible owing to the guarding potential 125 established at the "private-bank-contacts" of 130

such a "connector" as soon as the line is made busy by the first vertical step of the "first-selector" allotted to this line. It is for this reason, as previously set forth, that I provide means whereby this guarding or protecting potential is dis-established each time the subscriber grounds the so-called "rotary" side of his line,— that is, each time this is done after the "side-switch" of the "first-selector" has shifted to third position—thereby making it possible for a party-line subscriber to call his own line, and then cause the "connector-side-switch" to shift to third position at the moment that the guarding potential is removed from the "private-bank-contacts" of the "connector." Consequently in a case of this kind, there is a temporary abatement or cessation of the guarding potential just at the time that it would usually be depended upon to effect a release of the "connector," as, for example, when some other subscriber attempts to make connection with the calling subscriber's line. This guarding potential is, however, fully capable of precluding all possibility of a seizure of a busy line by some other subscriber, notwithstanding the improved arrangement by which I render the said guarding potential incapable of preventing a party-line subscriber from calling and obtaining connection, so to speak, with his own line. Each "first-selector," as herein shown and described, has a new bridge-cut-off-relay arrangement, each of these relays having two energizing circuits. The so-called "private-normal-relay" with which each "first-selector" is provided constitutes a new feature or adjunct for a switching machine of this character, and controls the two circuits of the bridge-cut-off-relay allotted to the "selector" to which it belongs. It will be seen that one energizing circuit of the said bridge-cut-off-relay includes the normally-open contacts of its associated "private-normal-relay," while the other energizing circuit of the same bridge-cut-off-relay includes not only the normally-closed contacts of the same "private-normal-relay," but also a couple of normally-open contacts of the bridge-cut-off-relay itself. The "private-normal-relay," however, has but one energizing circuit, namely, the ground-circuit including the "rotary-line-conductor" of the line to which the "selector" belongs, the switch-contacts 120 and 135, the bridge-cut-off-relay-springs 170 and 171, and also the other springs 172, 173 and 174 of the bridge-cut-off-relay, and thence to the non-grounded pole of the battery.

In the "connector", the construction is of any known or suitable character, with the exception, however, of the provision of but one tooth on the upper spring of the "private-magnet-armature-arm"; for, as explained, it is necessary that the "side-switch" of the "connector" be permitted to shift to third position as soon as the "private-magnet" of the "connector" is energized, and while the "private-normal-relay" of the "selector" remains energized; for if the "side-switch" of the "connector" should not escape to the third position until the "private-magnet" of the "connector" became de-energized, and until after the said "private-normal-relay" became de-energized, the desired results would not be accomplished. For example, if the "side-switch-escapement-device" had the old arrangement of two teeth above as well as below the bridge-cut-off-relay of the "first-selector" would never become energized, as the initial energizing circuit of this bridge-cut-off-relay includes the "private-shaft-wiper" and the "side-switch-wiper" of the "connector", the ground G and the contact-point 373; and consequently the "connector-side-switch" must shift to third position while the "private-normal-relay" remains energized. As soon as the "connector-side-switch" has shifted to third position, and the "private-normal-relay" has been de-energized, the energizing circuit of the bridge-cut-off-relay is then over the same path through the "connector", but does not include the same contacts in the "first-selector"; for this second energizing circuit of the bridge-cut-off-relay includes the contacts 175 and 176, the contacts 191 and 193, and the springs 184 and 185 of the bridge-cut-off-relay itself. With the arrangement shown, it will also be seen that each party-line is provided with a set of "multiple-connector-bank-contacts" or terminals which are multiplied together horizontally, and which are located in a certain level (the first level of the "connector-banks", with the arrangement shown) of the group of "connectors" allotted to one subscriber on the party-line, and to all other subscribers in the exchange whose numbers belong to the same hundred-group. Also, attached to the same party-line, there is another set of multiple-contacts or line-terminals which are multiplied together horizontally, and which are located in the same or corresponding level of another group of "connectors", this second group of "connectors" corresponding to the hundred-group of subscribers to which the next subscriber on the party-line belongs. In addition, the same party-line has attached to it a third set of multiple-contacts or line-terminals, located in the third group of "connectors"; and, finally, with the arrangement shown, there is a fourth set of multiple-contacts or line-terminals connected with the same party-line and located in the first level of a fourth group of "connectors". As explained, and as shown in Fig. 2 for example, the members of each set of contacts or line-terminals are multiplied together horizontally, and the four sets belonging to

four distinct and separate sets of "connectors" are then also multiplied together vertically, this latter method of connection being known as cross-multiplying. In this 5 way, a party-line having four subscribers thereon will be provided with four sets of line-terminals, each set consisting, for example, of ten terminals, and each terminal being located in a different "connector".

10 With this arrangement, there are ten "connectors" any one of which is capable of making connection with the said party-line, but only for the purpose of signaling and communicating with one of the subscribers 15 on the line. There are also ten more "connectors" each of which is capable of making connection with the said party-line, but only for the purpose of signaling and communicating with another subscriber on the 20 same line. The "connectors" of the third group, which are also ten in number, are each capable of making connection with the said party-line, but only for the purpose of signaling and communicating with the third 25 subscriber on the same line. Finally, any one of the ten "connectors" included in the fourth group may be employed for signaling and communicating with the fourth subscriber on the same line. When any one 30 of these "connectors" is employed by a party-line subscriber for calling his own line, in order to communicate with another subscriber on the same line, the "private-normal-relay" of the "first-selector" necessarily 35 employed in making connection with the "connector" causes a momentary cessation of the guarding potential at the "private-bank-contacts" corresponding to said line, thereby permitting the "connector" to establish 40 the connection without being subjected to an automatic releasing action, as would be the case without my improved arrangement. It will be seen, however, that a "connector" of this particular nature can also be employed 45 for establishing connection between two subscribers' lines, in the ordinary manner, and that in such case the "private-normal-relay" of the calling subscriber's "first-selector" will not have any control over any guarding 50 potential which may happen to exist at the "private-bank-contacts" corresponding to the called subscriber's line; for it is obvious that the calling subscriber's "private-normal-relay" is operative to cause a momentary abatement or cessation of the guarding potential at the line-terminals of his own line, for the purpose of permitting him to establish a connection with his own line, but is incapable of interfering in any way or to 55 any extent with any guarding potential which may have been established at the "private-bank-contacts" corresponding to any other line. In this way, any "connector" which may be employed by a calling subscriber for establishing connection with any

other line will be subjected to an automatic release, in the usual and well-known manner, in case the "private-shaft-wiper" of such "connector" encounters a guarding potential at the "private-bank-contact" corresponding to the called subscriber's line. Thus, any calling subscriber always rings only the bell at the called subscriber's station, providing the called subscriber's line is not busy, and regardless of whether the 75 called subscriber's station is the only station on the line, or is simply one of several subscribers' stations on the same party-line; and this is also the inevitable result regardless of whether the called subscriber's station 80 is on the calling subscriber's line or on another and separate line.

It will be seen that the bridge-cut-off-relay of the "selector" is only energized when the subscriber calls his own line, or when 85 some other subscriber calls the same line. When another subscriber calls the party-line shown, for example, it is desirable, of course, to have the bridge-cut-off-relay of the "selector" energized for the purpose of 90 opening the bridge containing the "line-relays" of the "selector" allotted to this party-line. When a subscriber on this line calls another subscriber on the same line, then it is desirable to have the bridge-cut-off-relay 95 energized for several reasons. For example, it is desirable that the bridge of the "selector-line-relays" be opened up or disconnected; but in addition to this, it is also desirable, at this time, to open up the "rotary- 100 line-conductor" between the "rotary-side-switch-wiper" and the "rotary-shaft-wiper", so as to prevent ringing current from passing back over the connection established with the "connector"; and it is also desirable, 105 as previously explained, to at this time remove the ground G^s from the spring 185, and to place this spring in contact with the spring 184; for these two contacts, when thus closed, constitute a part of the energizing circuit by which the bridge-cut-off-relay is retained in its energized condition during 110 conversation between two subscribers on the same party-line.

What I claim as my invention is:

1. An automatic telephone system comprising a "selector" provided with a "private-normal-relay" having normally-open and normally-closed contacts, a "private-normal-conductor", and a grounded battery, 120 said conductor being normally connected to said battery through the contacts of said relay.

2. An automatic telephone system comprising a "selector" provided with a "private-normal-relay" and a bridge-cut-off-relay, together with a "private-normal-conductor" connected with one of the contacts of said "private-normal-relay", and an energizing circuit for said "private-normal- 125

- relay" including normally-closed contacts of the said bridge-cut-off-relay.
3. An automatic telephone system comprising a "selector" provided with normally-bridged "line-relays", a bridge-cut-off-relay, and an energizing circuit for said bridge-cut-off-relay including some of its own contacts.
4. An automatic telephone system comprising a "selector" provided with a bridge-cut-off-relay having normally-open contacts, and an energizing circuit for said bridge-cut-off-relay including said normally-open contacts.
5. An automatic telephone system comprising a "selector" provided with a bridge-cut-off-relay, a "private-normal-relay", a "private-normal-conductor" connected with the normally-closed contacts of said "private-normal-relay", and an energizing circuit for said bridge-cut-off-relay including the said "private-normal-conductor" and normally-closed contacts, and also including some of the contacts of the bridge-cut-off-relay.
6. An automatic telephone system comprising a "selector", a bridge-cut-off-relay therefor, and an energizing circuit for said bridge-cut-off-relay, said circuit being provided with a normally-open switch-point controlled by the "selector", a normally-open switch-point controlled by the bridge-cut-off-relay itself, a normally-closed switch-point and a relay for controlling the same.
7. An automatic telephone system comprising a "selector" provided with "vertical" and "rotary" relays, a "private-normal-relay", and an energizing circuit for said "private-normal-relay", together with an energizing circuit for the said "rotary-relay", and means for closing said circuits simultaneously.
8. An automatic telephone system comprising a switch individual to a single subscriber, or to a group of subscribers on one line, provided with a "private-normal-relay" having normally-open and normally-closed contacts, a "private-normal-conductor," and a battery, said conductor being normally grounded through the medium of said battery and the contacts of said relay.
9. An automatic telephone system comprising a switch individual to a single subscriber, or to a group of subscribers on one line, provided with a "private-normal-relay" and a bridge-cut-off-relay, together with a "private-normal-conductor" connected with one of the contacts of said "private-normal-relay", and an energizing circuit for said "private-normal-relay" including normally-closed contacts of the said bridge-cut-off-relay.
10. An automatic telephone system comprising a switch individual to a single subscriber, or to a group of subscribers on one line, provided with normally-bridged "line-relays", a bridge-cut-off-relay, and an energizing circuit for said bridge-cut-off-relay including some of its own contacts.
11. An automatic telephone system comprising a switch individual to a single subscriber, or to a group of subscribers on one line, provided with a bridge-cut-off-relay having normally-open contacts, and an energizing circuit for said bridge-cut-off-relay including said normally-open contacts.
12. An automatic telephone system comprising a switch individual to a single subscriber, or to a group of subscribers on one line, provided with a bridge-cut-off-relay, a "private-normal-relay", and a "private-normal-conductor" connected with the normally-closed contacts of said "private-normal-relay", and an energizing circuit for said bridge-cut-off-relay including the said "private-normal-conductor" and normally-closed contacts, and also including some of its own contacts.
13. An automatic telephone system comprising a switch individual to a single subscriber, or to a group of subscribers on one line, a bridge-cut-off-relay therefor, and an energizing circuit for said bridge-cut-off-relay, said circuit being provided with a normally-open switch-point controlled by the said switch, a normally-open switch-point controlled by the bridge-cut-off relay itself, a normally-closed switch-point, and a relay for controlling the same.
14. An automatic telephone system comprising a "selector", "line-relays" for the "selector," a bridge-cut-off-relay for opening up or disconnecting the bridge in which the "line-relays" are normally included, said "selector" having a rotary "side-switch-wiper" and a rotary shaft-wiper, and said bridge-cut-off-relay being adapted when energized to open the "rotary" side of the "line-circuit" at a point between the said wipers.
15. An automatic telephone system comprising a "selector" provided with a normally-closed bridge, containing operating elements bridged across the conductors of the talking circuit, and a bridge-cut-off-relay, said bridge-cut-off-relay being adapted when energized to both open up said bridge and open or break the so-called "rotary" side of the "line-circuit" of the said "selector."
16. An automatic telephone system comprising a "selector" provided with normally-bridged "line-relays", and having a bridge-cut-off-relay, together with a "private-normal-conductor" adapted to be grounded through normally-closed contacts of said bridge-cut-off-relay, the said bridge-cut-off-relay being adapted when energized to both open up said bridge and separate the said contacts included in the normally-closed

- connection between the said "private-normal-conductor" and the ground. 65
17. An automatic telephone system comprising a normally-closed electromagnetic bridge across the conductors of the talking 5 circuit, a bridge-cut-off-relay, and an energizing circuit for said relay including some of its own contacts. 70
18. An automatic telephone system comprising a normally-closed electromagnetic bridge across the conductors of the talking 10 circuit, a bridge-cut-off-relay provided with normally-open contacts, and an energizing circuit for said relay including said contacts. 75
19. An automatic telephone system comprising a line, an "individual-switch" therefore provided with an electromagnetic bridge across said line, and a bridge-cut-off-relay 20 having an energizing circuit which includes some of the contacts of said relay. 80
20. An automatic telephone system comprising a line, an "individual-switch" therefore provided with an electromagnetic bridge 25 across said line, and a bridge-cut-off-relay having an energizing circuit which includes two of the normally-open contacts of said relay. 85
21. An automatic telephone system comprising a "selector" provided with "vertical" and "rotary" "line-relays" normally bridged across the "line-circuit" of the "selector", a bridge-cut-off-relay, a "private-normal-relay" controlling the operation of said 30 bridge-cut-off-relay, a "private-normal-conductor" terminating in one of the contacts of said "private-normal-relay", a battery having one pole grounded and the other pole 35 suitably connected with one terminal of the coil of said bridge-cut-off-relay, the non-grounded pole of the battery being also connected with the coils of both "line-relays", and with the "private-normal-relay", through the medium of some of the contacts 40 of the said bridge-cut-off-relay. 90
22. An automatic telephone system comprising a "connector" provided with a "side-switch", a "private-magnet" controlling said "side-switch", and an escapement device for 45 said "side-switch" operated by said magnet, said escapement device comprising two lower teeth and only a single upper tooth, together with a finger carried by the "side-switch" and adapted to cooperate with said 50 teeth in permitting the "side-switch" to shift from first to second and from second to third position, and means for controlling the connector over the line circuit extended thereto. 95
23. An automatic telephone system comprising a "connector" provided with a "side-switch" having three distinct or operative 55 positions, a "private-magnet" controlling said "side-switch", and means whereby the "side-switch" is permitted to shift to second position upon the energizing and de-energizing of the "private-magnet" for the first time, and then from second to third position as soon as the "private-magnet" is again energized, and means for controlling the connector over the line circuit extended thereto. 100
24. In a telephone exchange system the combination of a "connector" provided with a "side-switch", a "private-magnet" controlling said "side-switch", and an escapement device for said "side-switch" operated by said magnet, said escapement device comprising two lower teeth and only a single upper tooth, together with a finger carried by the "side-switch" and adapted to cooperate with said teeth in permitting the "side-switch" to shift from first to second and from second to third position, a line circuit, and means for controlling said connector over grounded circuits including one or the other of the line conductors of said line circuit. 105
25. In a telephone exchange system, the combination of a "connector" provided with a "side-switch" having three distinct or operative positions, a "private-magnet" controlling said "side-switch", means whereby the "side-switch" is permitted to shift to second position upon the energizing and de-energizing of the "private-magnet" for the first time, and then from second to third position as soon as the "private-magnet" is energized the second time, a line-circuit, and means for controlling said connector over grounded circuits including one or the other of the line conductors of said line circuit. 110
26. In a telephone exchange system, the combination of a line, ringers on said line, and subscriber-controlled means including centralized instrumentalities for supplying electric currents of different kinds for selectively operating said ringers over metallic circuits including both sides of the line. 115
27. An automatic telephone system comprising switching mechanism provided with shaft controlled springs, a bridge cut-off relay, a plurality of energizing circuits for said bridge cut-off relay controlled by said shaft controlled springs. 120
28. In an automatic telephone system, a party line having a plurality of stations thereon, other lines, switching mechanism provided with shaft controlled springs, a bridge cut-off relay, a plurality of energizing circuits for said bridge cut-off relay controlled by said shaft controlled springs, one of said circuits being used for calls to said party line from other lines. 125
29. In an automatic telephone system, a party line having a plurality of stations thereon, other lines, switching mechanism provided with shaft controlled springs, a

bridge cut-off relay, a plurality of energizing circuits for said bridge cut-off relay controlled by said shaft controlled springs, one of said circuits being used for calls to said 5 party line from other lines, the other of said circuits being used for calls from stations on the same line.

30. An automatic telephone system, a party line having a plurality of stations 10 thereon, switching mechanism provided with shaft controlled springs, a bridge cut-off relay, a plurality of energizing circuits for said bridge cut-off relay controlled by said shaft controlled springs, said bridge cut-off 15 relay being maintained energized when one station on said party line is connected with another station on said line.

31. An automatic telephone system comprising switching mechanism provided with 20 shaft controlled springs, a bridge cut-off relay, a plurality of energizing circuits for said bridge cut-off relay, two of said circuits controlled by said shaft controlled springs, another of said circuits controlled 25 by other means.

32. An automatic telephone system comprising switching mechanism provided with a private normal relay, a bridge cut-off relay, a private normal conductor connected 30 through contacts of said private normal relay to the winding of said bridge cut-off relay, and a path for voice currents exclusive of said private normal relay.

33. An automatic telephone system comprising switching mechanism provided with a private normal relay, a bridge cut-off relay, a private normal conductor normally connected to battery through the winding of 35 said bridge cut-off relay and contacts of said private normal relay, and a path for voice currents exclusive of said private normal relay.

34. In a telephone system, the combination of a telephone line, a plurality of 40 stations on said line, automatic means for establishing a guarding potential for said line as soon as a substation thereon begins calling, switching mechanism for establishing connection with the line, means including a relay having normally open and normally closed contacts for removing said 45 guarding potential to permit said switching mechanism to make connection with said line when one substation calls another on the same line.

35. In a telephone system, the combination of a telephone line, a plurality of sub- 50 stations on said line, automatic means for establishing a guarding potential for said line as soon as a substation thereon begins calling, switching mechanism for establishing connection with the line, a line relay for controlling said switching mechanism, means including a private normal relay for

removing said guarding potential to permit 65 said switching mechanism to make connection with said line when one substation calls another on the same line, said private normal relay connected in bridge of said line relay.

36. In a telephone system, the combination of a telephone line, a plurality of substations on said line, automatic means for establishing a guarding potential for said line as soon as the substation thereon begins calling, 75 switching mechanism for establishing connection with the line, means including a private normal relay normally connected to one pole of battery for removing said guarding potential to permit said switching 80 mechanism to make connection with said line, when one substation calls another on the same line.

37. In a telephone system, a line, a line relay individual to said line, a cut-off relay 85 for disconnecting said line relay, automatic directively controlled switches for extending connections to said line, means for momentarily closing an initial energizing circuit for said cut-off relay when one of said connections is established, and a locking circuit closed by said cut-off relay for maintaining itself energized after the initial energizing circuit is broken.

38. In a telephone system, a plurality of 95 automatic directively controlled connector switches, a plurality of different sources of ringing current associated with said connectors, respectively, a party line accessible in common to all of said connectors, signaling devices connected in bridge of said line at the subscribers' stations, each device being responsive to a different one of said sources, and means in each connector for connecting the associated source in bridge of said line 100 to operate the signaling device responsive thereto over a circuit including the two sides of said party line in series.

39. In a telephone system, a party line, a plurality of groups of connector switches 110 having access to said party line, ringing current sources of different character, each of said sources being assigned to a particular group of connectors, ringers connected in bridge of said line at the subscribers' stations, each ringer being adapted to respond only to a particular one of said sources, and means in each connector for connecting the associated ringing current source in bridge of said party line to operate the ringer corresponding to such source over a full metallic circuit.

40. In a telephone system, a party line, a plurality of groups of connector switches having access to said party line, ringing 125 current sources of different character, each of said sources being assigned to a particular group of connectors, ringers connected in

bridge of said line at the subscribers' stations, each ringer being adapted to respond only to a particular one of said sources, means including a selector switch whereby a 5 subscriber on a calling line can establish a connection with said party line by way of an idle connector in any one of said groups, the group selected depending on which station is wanted, and means in the connector 10 in use for connecting the associated ringing current source in bridge of said party line to operate the ringer at the desired station over a full metallic circuit.

41. In a telephone system, a party line, 15 sources of ringing current of different character, ringers connected in bridge of said line at the subscribers' stations, each ringer responsive only to current from a particular one of said sources, and automatic switching 20 mechanism controllable by a calling subscriber for bridging the source correspond-

ing to the ringer at any desired station across the line to signal such station over a full metallic circuit.

42. In a telephone system, a party line, 25 sources of ringing current of different frequency, tuned signaling devices connected in bridge of said line at the subscribers' stations, each device responsive only to current from a particular one of said sources, and 30 automatic switching mechanism controlled by a calling subscriber for bridging the source corresponding to the signaling device at any desired station across the line to signal such station over a full metallic circuit. 35

Signed by me at Chicago, Cook County, Illinois, this 12th day of July, 1905.

TALBOT G. MARTIN.
